projecting laterally from an arm 497 fastened to a rock shaft 498 projects. The initial movement of the shaft 438 places the right hand end of the elongated opening 495 in contact with the pin 496. And as the machine is operated the shaft 498 is rocked counter-clockwise by a further movement of the link 494 by mechanism to be hereinafter described.

Secured to the shaft 498 is an arm 499 having a pin 500 projecting into a slot 501 formed in a sliding coupler 502 guided in its movements by studs 503 mounted in a drawer plunger lever 504 and extending into a slot 505 in the sliding coupler. As the arm 499 moves counter-clockwise the coupler 502 moves forward, placing the shoulder 506 in a position to be contacted by a projection 507 on the arm 479 secured to the shaft 478. With the coupler 502 in this forward position, the counter-clockwise movement of the shaft 478 will cause the drawer plunger lever 504 to swing in a like direction and lift a drawer plunger 508 to release the cash drawer 473.

The drawer plunger is mounted in a base 509 of the frame with a spring 510 entwined about the plunger between a pin 511 and the base. A collar 512 secured to the drawer plunger, above the base, controls the lower position of the plunger. In the upper end of the plunger is a vertical slot, in which the drawer plunger lever freely operates. A horizontal pin 514 secured in the plunger passes through an elongated opening 515 formed in the drawer plunger lever. The opening 515 in the drawer plunger lever is elongated to permit the plunger to rise, when closing the cash drawer, without moving the lever and also to allow a greater movement of the lever than that required to lift the plunger.

A spring 516 attached to a stud 517 mounted in the base and to the arm 497 moves the shaft 498 clockwise to return the coupler 502 to normal position.

As the plunger rises it is withdrawn from a bracket 518 fastened on the back of the cash drawer, allowing a spring 519 to move the drawer forwardly. As the drawer moves forwardly a bell crank lever 520 freely mounted upon the shaft 498 moves clockwise under the action of a spring 521 (Fig. 42) until an ear 523 formed on the lever 520 engages a shoulder 522 formed on the link 494 which has been moved forwardly during the operation of the machine. With the link 494 latched in its forward position the totalizing lever 172 cannot be returned to the adding position. This condition makes it necessary to return the cash drawer to its normal position, which moves the lever 520 counter-clockwise and moves the ear 523 from the path of the shoulder 522 on the link 494.

The drawer plunger lever, in addition to releasing the cash drawer, operates the bell mechanism. The forward end of this lever 504 has a formed ear 528 which normally contacts a pin 529 projecting laterally from a bracket 530 secured to the base 509. Freely mounted upon a stud 531 secured in the bracket 530 is a bell hammer 532. In the normal position of the hammer a shoulder 533 thereon engages a pin 534 projecting laterally from the bracket 530. This hammer is retained in its normal position by a spring 535 attached to a pin 536 on the frame and to a trip pawl 537 freely mounted in a stud 538 secured in the bell hammer. The trip pawl 537 has a forwardly extending arm 539 normally in contact with a pin 540 on the hammer, and also an upright extending arm 541 in the plane of the ear 528 on the drawer plunger lever 504. As the drawer plunger lever moves counter-clockwise the ear 528 engages the arm 541 and causes the bell hammer to move clockwise on its pivot until the ear disengages from the arm, as the ear and arm rotate in opposite directions, at which time the bell hammer returns to normal position under the tension of the spring 535. A pin 542 mounted in the arm 479 contacts a projection 543 extending downwardly from the drawer plunger lever, and as the shaft 478 moves clockwise this lever is returned to normal position.

Printer.—The printing mechanism is located on the left hand side of the machine proper, and prints and issues a receipt 550 (Fig. 29) containing the date, consecutive number of the transaction, the amount of each item entered in the transaction, together with a total of the same, characters representing the class of transaction, the word "Total" and other selected data. In addition to the receipt, a record strip 551 (Fig. 28) is printed and retained within the machine, having a total of each transaction together with the classification character.

The nested sleeves 249 and shaft 250 (Figs. 19 and 40) actuated by arms 247 and 266 controlled by the differential mechanism, as previously described, support at their left hand ends segments 552 which mesh with teeth 553 of segment levers 554 freely mounted upon a stud 555 projecting laterally from the side frame 82. The upper ends of the segment levers 554 have teeth 556 in mesh with teeth 557 of partial gears 558 secured to nested sleeves 559 and a shaft 560 supported by the left hand frame 82 and a plate 561 (Fig. 24). Secured to the left hand end of the sleeves 559 and shaft 560 are item type printing wheels 562 and a transaction character wheel 563. Each type wheel has two sets of type characters to permit of impressions

UNITED STATES PATENT OFFICE

BERNIS M. SHIPLEY, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed December 21, 1922. Serial No. 308,281.

This invention relates to cash registers and machines, and more particularly to machines of the type shown and described in Letters Patent of the United States No. 1,289,864, issued to W. A. Chryst on June 26, 1917, and Nos. 1,242,170 and 1,394,256, issued to F. L. Fuller on October 9, 1917 and October 18, 1921, respectively, and in Letters Patent of the United States, No. 1,479,796, granted to B. M. Shipley on March 1, 1927.

It is an object of this invention to provide mechanism for printing and issuing an itemized receipt with total, a transaction classification character, and other matter of any desired wording, and for simultaneously printing the total upon a record strip retained in the machine.

Another object is to provide mechanism for indicating each item and its classification as the item is recorded, and for indicating the total of the items involved in a transaction, together with its classification, when the total is recorded.

Another object is to provide counting mechanism for counting the number of transactions of various classifications.

Another object is to provide a counting mechanism for counting the number of items recorded, and a separate counting mechanism for counting the number of customers.

Another object is to provide mechanism for disabling the receipt issuing mechanism when printing upon the total record strip the totals of the classified totalizers.

Another object is to provide mechanism for retaining a transaction key in the depressed position until released by depressing another transaction key or a special release key.

Another object is to provide one set of printing wheels for printing, both the items and the total, and a plurality of impression platens for obtaining the various impressions.

With these and incidental objects in view, the invention consists of certain novel features of construction and combinations of parts, the essential elements of which are set forth in appended claims and a preferred

form or embodiment of which is hereinafter described with reference to the drawings which accompany and form part of this specification.

Of said drawings:

Fig. 1 is a perspective view of the machine.

Fig. 2 is an elevation of the machine looking at the right hand end, parts being removed for the sake of clearness.

Fig. 29 is a view showing the receipt issued by the machine.

40 Fig. 30 is an elevation of the printer.

Fig. 31 is a detail view showing the type line and printing hammers in front elevation.

45 Fig. 32 is a detail view of a manually operated means for throwing off the check, the consecutive numbering device, and the upper printing hammers.

Fig. 33 shows means for automatically controlling the item printing hammer.

50 Fig. 34 is a transverse section taken through the printer on the line 34—34 of Fig. 24.

Fig. 35 shows means for automatically controlling the upper total, the electro, and the date printing hammers.

Fig. 36 is a detail view of the ribbon feeding mechanism.

Fig. 37 is a detail front elevation showing 60 the date and consecutive numbering devices.

Fig. 38 is a section taken through the date setting mechanism on line 38—38 of Fig. 37.

65 Fig. 39 is a section taken through the consecutive numbering device on line 39—39 of Fig. 37.

Fig. 40 is a sectional view taken on the line 40—40 of Fig. 24.

Fig. 41 is a detail plan view of the drawer opening and bell ringing mechanisms.

Fig. 42 is a detail view showing the interlocking mechanism between the totalizer control lever and the drawer mechanism. 70

Fig. 43 is an elevational view of the mechanism shown in Fig. 41.

In general

75

Described in general terms, the machine in its preferred form includes a plurality of totalizers, one for each classification of transactions, and one for totalizing each separate transaction. These totalizers are operated by differential mechanisms under the control of the manipulative means, in this case, the amount keys. 80

The differential mechanism provides means for adjusting the printing mechanism to print on the issuing receipt, the amounts entered in the totalizers, together with the total of the same, and also to print on the record strip, transaction and classification totals. 85

The differential mechanism also provides means for adjusting the indicating mechanism to indicate the amount of each item recorded and the total of the items of a 90 transaction.

The printing mechanism includes a single amount type line, date type wheels, consecutive number type wheels, and suitable electro. The amount and transaction type wheels are set differentially by tube lines and a train of gears. The date type wheels are set by manually operated knobs in the usual manner. The consecutive number type wheels are operated by a differentially timed pawl. 100

This machine, in its present embodiment, is especially adapted for use in places of business where it is desirable to issue an itemized printed receipt to the customer and also retain in the machine a record strip containing the totals of each transaction. 110

When the total of a transaction is printed the transaction totalizer is restored to normal or zero position. A sub-total from a classification totalizer may be printed and the totalizer not restored to zero, or a total may be printed and the totalizer restored to zero. 115

Operating mechanism.—The machine is 120 manually operated by a handle 55 (Figs. 1 and 2) provided with a stud 56 extending into a short tubular bearing secured to the right hand frame of the machine. Connected to the handle 55 is a pinion 57 meshing with a gear 58 mounted on a stud 59 projecting from the frame of the machine. The gear 58 meshes with a gear 60 secured on the main driving shaft 61. The ratio 125 of the pinion 57 and gear 60 is such that 120

two rotations of the handle will cause one rotation of the shaft 61.

The machine may also be operated by an electric motor of the well known type illustrated and described in Letters Patent of the United States No. 1,144,418, granted to Charles F. Kettering and William A. Chryst on June 29, 1915. For a detailed description of the same, reference may be had to that patent. Only a part of the motor frame and the switch for the motor, and a part of the clutch mechanism for the motor are shown in the accompanying drawings.

The motor is carried by a frame 62 (Fig. 30) mounted on the left side frame of the machine. A clutch shell 63 (Figs. 25 and 27), forming one part of the clutch device, and shown in section in Fig. 27, is rotated by a worm 64 (Fig. 30) secured to the armature shaft of the motor and in mesh with a worm gear 65 secured to the clutch shell 63. A plate 66 (Fig. 27), forming another member of the clutch cooperates with rollers 67 carried by a disk 68 and is connected thereby to the clutch shell 63 upon release of the machine, as fully shown and described in the aforesaid Kettering and Chryst patent. The disk 68 has a shoulder 69 (Fig. 25) contacting the end of a lever 70 (Fig. 40) mounted on a stud 71 on the frame of the machine. An arm 72 (Fig. 40) secured to the lever 70 carries a pin 73 which normally rests on a curved edge 74 of an arm 75 freely mounted on a shaft 76, journaled in the printer frame. The arm 75 is connected by a link 77 to a bell crank lever 78 secured to a shaft 79 extending across the entire machine, and journaled in the frames thereof. When the bell crank lever 78 is rocked clockwise to release the machine, as will hereinafter be described, the arm 75 is rocked clockwise from underneath the pin 73, to permit a spring 80, attached to the arm 72 and to a pin 81 (Fig. 24) projecting from a printer frame 82, to move the lever 70 out of the path of the shoulder 69. The clockwise movement of the lever is limited by a pin 84 (Fig. 40) projecting from the frame of the machine. Upon release of the lever 70 the disk 68 is moved forwardly by spring actuated plungers 85 (Fig. 27) to move the rollers 67 into operative position, as is fully described in the above mentioned Kettering and Chryst patent. The movement of the lever 70 also releases a spring actuated disk 86 which, as it moves in a clockwise direction, rocks a yoke 87 pivoted on a stud 88 (Fig. 26) counter-clockwise, and thereby closes the circuit through the motor. One side of the yoke 87 carries a roller 89 contacting the disk 86. The opposite side of the yoke engages a roller 90 (Fig. 30) carried on an arm 91, provided with an insulating block 92 to lower a switch blade 93 into contact with a switch

blade 94, thereby closing the circuit through the motor. The clutch plate 66 (Fig. 27), is fastened on a sleeve 95 mounted on a stud 96 on the frame of the machine. A gear 97 (Figs. 25 and 40), secured on the sleeve 95 meshes with a gear 98 on a stud 99 on the frame of the machine. This gear 98 also meshes with a gear 100 fastened to the shaft 76, rotated once at each operation of the machine. Secured to the gear 98 is a gear 101 meshing with a gear 102 fastened to the shaft 61, which rotates once at each operation of the machine.

The lever 70 is restored to locking position, near the end of the operation of the machine, by a cam 103 (Fig. 40) secured to and rotating with the shaft 76. This cam contacts an extension 104 on the arm 72 and moves the lever 70 in a counter-clockwise direction to move the lower end of said lever 70 into the path of the shoulders on the various clutch members to stop the machine, as is fully described in the Kettering and Chryst patent previously referred to. As the lever moves in a counter-clockwise direction, the pin 73 is elevated above the curved edge on the lever 75, permitting said lever to return to normal position by a counter-clockwise movement of the shaft 79, which will hereinafter be described.

When the machine is operated by the motor, an auxiliary device is applied to assist in bringing the rotating shaft 61 (Fig. 2) and its cooperating parts, to a normal or home position at the end of an operation. This device consists of a cam 105 secured to the shaft 61 and cooperating with a roller 106 carried by a stud mounted on an arm 107 pivoted at a point 108. A spring 109 is attached to the right hand end of this arm and to a pin projecting from the side frame of the machine. As the shaft 61 rotates clockwise, the arm 107 is moved in a like direction and gradually increases the tension on the spring until near the end of the operation, when the contour of the cam permits a rapid return of the arm 107 by the spring 109.

Keyboard.—The keyboard mechanism of the present machine is the same as that shown and described in the Shipley Patent No. 1,619,796, and reference is hereby made thereto for a full and clear description of the same. Only a brief description of the keyboard and its cooperating mechanism will be given herein.

The keyboard includes four banks of amount keys, one bank of transaction or classification keys, a key for releasing a depressed transaction key, a starting key, and a total lever to control the machine for total and sub-total printing.

The keys 110 of each amount bank are mounted in an individual frame 111 (Fig. 18) mounted on cross rods 112 carried by

the machine frame. The keys are retained in their normal outward positions by compression springs 113.

When a key is depressed it cooperates with a detent 114 (Fig. 19) and is thereby retained in its depressed position, as is well known in the art. Each bank is provided with a zero stop pawl 115, pivoted to the frame of the bank and adapted to be rocked to ineffective position upon the depression of any key in the bank, and held in this position until the parts are again returned to normal.

The present machine is normally released for operation by the depression of the starting key 116 (Fig. 14), which releases the shaft 79 to rock clockwise (Figs. 14 and 40), to move the arm 75 from beneath the stud 73 to release the motor as before described. Depressing the starting key moves a pin 118 (Fig. 14), projecting from the key, into contact with an inclined wall 119 of a notch in a release bar 120 supported by links 121 and 122 pivoted on studs 123 and 124 fastened in a key frame 125. The link 121 (Figs. 14 and 17) has a laterally projecting pin 126 cooperating with a slot 127 in an arm 128 pivoted upon a rod 129 which extends through the machine and is supported at each end by the frames of the machine. As the starting key pin 118 contacts the release bar 120 the arm 128 is rocked in a counter-clockwise direction. Fastened to the arm 128, by a rivet 130 and a stud 131, is release pawl 132, which is freely mounted upon the rod 129 and moves with the arm 128. As the release pawl 132 moves in a counter-clockwise direction it moves out of contact with the flat side of a pin 133 on an arm 139, connected to the shaft 79 in a manner to be presently described. As the arm clears the pin 133 it permits the shaft 79 to rock clockwise, to release the motor clutch mechanism, previously described. A non-repeat pawl 136 freely mounted upon the rod 129 is normally held in contact with the lower side of the pin 133 by a spring 137 attached to a pin secured in the non-repeat pawl 136 and to a pin secured to the arm 132. Should the starting key be held depressed during the entire operation of the machine the non-repeat pawl 136 moves counter-clockwise in front of the flat surface of the pin 133, as the pin moves toward the right during the operation, and prevents a repeat operation. The release pawl 132 is formed so as to overlap the edge of the non-repeat pawl 136 at the point 138 to return the non-repeat pawl to its normal position. The flat sided pin 133 is mounted in an arm 139 projecting from a sleeve 140 freely mounted upon the shaft 79 (Fig. 15). This sleeve has a finger 141 extending forwardly to engage a pin 142 mounted in an arm 143 secured to the shaft 79 (Figs. 15 and 16).

An arm 144 (Figs. 2 and 15) is fastened to the shaft 79 outside the right hand frame of the machine. The arm 144 carries a screw stud 145 upon which are pivoted two spring clips 146, placed on each side of a link 147 slotted to move over the stud. A coil spring 148 surrounding the lower ends of these clips is compressed between shoulders on said clips and the lower wall of a slot 149 in the link 147. From this it can be seen that as the starting key is depressed and pawl arm 132 (Fig. 17) moved counter-clockwise, the spring 148 (Fig. 2) is released to rock the shaft 79 clockwise to release the motor clutch mechanism, previously described. The movement of the shaft 79 is limited by a finger 150 on the arm 144 and a stud 151 projecting laterally from the frame.

The starting key 116 (Fig. 14) cannot be depressed to release the machine for operation until one of the transaction keys 152 is depressed. A pin 153, projecting laterally from a detent 154, is normally in the path of a shoulder 155 on the starting key. When a transaction key is depressed a projection 156 thereon contacts a pin 157 mounted on the detent 154 and moves the detent downwardly and the pin 153 out of the path of the shoulder on the starting key.

After a transaction key is depressed it can be released only by depressing another transaction key or by depressing the release key 158, which has an inclined edge 159 contacting a pin 160 mounted in the detent 154.

The transaction keys cannot be depressed while the starting key is held in its depressed position, because when the starting key is depressed the projections 161 on the release bar 120 are moved into the path of key pins 162. The release bar 120 is held in normal position by a spring 163.

The amount keys 110 (Fig. 19) are also locked against manipulation after the starting key is depressed by a universal rod 168, carried between arms 167 secured to the shaft 79. The universal rod 168 extends into a slot 169 in a link 170 pivoted on a stud 171 for each bank of amount keys. This link is connected to a locking bar (not shown) which, when the shaft 79 is rocked in a counter-clockwise direction, is moved into position to lock out the aforesaid keys, as is fully described in the Shipley patent 1,615,110 previously referred to.

Depressing the starting key also locks the totalizing lever 172 (Fig. 5) against manipulation. The pin 181 (Fig. 17), projects into a slot 173 in a yoke 174 freely mounted upon the shaft 79. The left hand side of the yoke has a laterally projecting pin 175 contacting an angle edge 176 formed on a second yoke 177 freely mounted upon the rod 129. After the starting key is depressed,

the yoke 177 is moved clockwise, causing an ear 178 to enter one of several slots 179 (Fig. 5) in the totalizing lever plate 166. A spring 180 normally holds the ear 178 of the yoke 177 out of the slot 179.

Near the end of the operation of the machine the parts operated by the depression of the starting key are restored to their normal positions by a cam 181 (Fig. 2) formed in the gear 58. Cooperating with this cam is a roller 182 mounted on a stud carried by a lever 183 freely mounted on a stud 184 projecting from the side frame of the machine. The upper end of the lever 183 carries a pin 185 which normally engages a slot 186 formed in the link 147. As the gear 58 rotates, the arm is moved first clockwise and then counter-clockwise, which causes the link 147 to move downward and return. When the machine is released for operation, the stud 145 moves against the upper wall of the slot in the link 147, and, therefore, when the lever 183 lowers the link 147, the shaft 79 is rocked counter-clockwise. This movement of the shaft 79 moves the pin 142 (Fig. 16) into contact with a lever 187 freely mounted on the shaft 129. As this lever is moved counter-clockwise its lower end 188 contacts a pin 189 mounted in the arm 139 and moves this arm in a counter-clockwise direction, which restores the pin 133 (Fig. 17) to its normal position, allowing all other parts cooperating with said pin to return to their normal positions. The total lever 172 is provided for the purpose of controlling the machine in total and sub-total printing operations.

Differential mechanism

The differential mechanism of the machine is employed to operate the different totalizers, to select them for operation, and also to set type carriers, in the printing mechanism, as controlled by the banks of amount keys and the bank of transaction keys. The amount differential mechanism will be described first.

Differential—Amount banks.—There is a differential unit for each of the four amount key banks and two extra units of higher denominations operated in adding operations only when a transfer to them is necessary. Each unit is supported by hangers 195 and 196 (Figs. 18, 19 and 20) mounted upon rods 197. A rod 198 extends through all of the differential units, including the transaction unit, and acts as a stabilizer for said units.

Each differential unit is driven by a pair of cams 199 and 200 fixed on the shaft 61. These cams cooperate with rollers 201 and 202 respectively on a Y-shaped lever 203 pivoted on a stud 204 on the hanger 195. The pairs of cams 199 and 200 are arranged spirally on the shaft 61, that is, the units

cams are set slightly ahead of the tens cams, the tens cams slightly ahead of the hundreds cams, etc. This arrangement of cams is illustrated in the above mentioned Chryst Patent No. 1,230,864 and is for the purpose 70 of entering transfers successively as is well known in the art.

To the upper end of the lever 203 is pivoted a link 208 pivoted to a driving segment 209 loose on a hub 210 fastened in the hanger 196. The cams 199 and 200 (Fig. 19) oscillate the lever 203 first counter-clockwise and then clockwise to normal position, thus movement through the link 208 rocking the driving segment 209 first counter-clockwise 80 and then clockwise to its normal position.

There are two totalizer actuating segments 211 in each unit, mounted between and secured to two nearly circular disks 212 and 213 having fast thereto a hub (not 85 shown) journaled on the hub 210. The actuating segments 211 operate totalizer pinions 214 of the front and back totalizer lines, to be hereinafter described. The differentially movable disks 212 and 213 are 90 connected to the invariably movable segment 209 by a latch 215 carried by a bell crank 216 and a link 217 pivoted at 218 and 219 respectively to the disks 212 and 213. A foot 95 221 of the latch 215 is normally held in contact with the segment 209 above a shoulder 222 by a spring 223 (Fig. 18) stretched between the upper end of the bell crank 216 and a pin mounted in the plates 212 and 213.

By this latch connection the plates 212 100 and 213 and segments 211 are rotated counter-clockwise (Fig. 19) until an arm 224 of the bell crank 216 strikes the end of a depressed key. When this occurs the bell crank 216, link 217 and latch 224 are moved 105 clockwise, thereby removing the foot 221 from the shoulder 222. The foot 221 then rides upon the outer periphery of the segment 209 as the segment continues its invariably movement. When the latch is thus disconnected the forward end thereof engages a notch 228, opposite the depressed key, in a plate 229 mounted upon the rod 197 and the upper end of the hanger 195. There are ten notches 228 in the plate 229, 110 one for each of the nine keys, and one at the zero position. When there is no amount key depressed the latch is disconnected in the zero position. Adjacent the disk 212, and pivoted on the center 198, is a reset 115 spider 230 (Fig. 18) having an arm 231 provided with a slot into which a stud 232 carried by the arm 224 projects. The arm 231 is in the plane of the zero stop pawl 115, and when there is no key depressed the 120 upper edge of the arm 231 strikes the pawl 115, thereby disconnecting the latch 215 from the driving segment 209. This arrests the rotation of the segments 211 and their supporting members. When the driv- 125

ing segment 209 is rotated clockwise the pawl 115 is moved into the slot 231 and the latch 215 is again held in contact with the segment 209.

ing segment 209 is rocked clockwise (Fig. 19) it contacts a pin 233 carried by the disks 212 and 213 and rotates the said disks to their normal positions during which time 5 the actuating segments 211 add upon the totalizer pinions. The time when the actuating segment 209 contacts the pin 233 varies according to the key depressed. The totalizer pinions 214, by means to be hereinafter described, are rocked into mesh with the actuating segments 211 just after the latches 215 have been disconnected so that as the actuating segments 211 are returned to their normal positions the 10 amounts, as determined by the depressed keys, are accumulated on said pinions.

Differential—Transfer.—When one of the totalizer pinions 214 passes from the "9" to the "0", a transfer mechanism is tripped 20 for causing "1" to be added upon the totalizer pinion of the next higher denomination. Pivotaly mounted between the disks 212 and 213 on pins 234 (Fig. 19) are arms 235 each having two teeth like the teeth of 25 the actuating segment 211. These arms are in the plane of the segments.

The transfer tripping mechanism associated with these arms 235 for the two totalizer lines is the same as that fully described in the Shipley patent previously referred to.

Associated with the differential mechanism is a beam 241 (Fig. 19) pivoted on a stud 242 carried by the disks 212 and 213. 35 The beam has a slot 243 receiving a pin 244 on a link 245 pivoted to a segment 246 to be hereinafter described in connection with the indicating mechanism. The link 245 is connected to an arm 247 by a pin 248 on 40 the arm. The arm 247 is secured to one end of a telescopic sleeve 249. There is one of these sleeves for each amount bank supported by a shaft 250 journaled in the frame of the machine. The purpose of these 45 sleeves will hereinafter be described in connection with the printing mechanism.

Differential—Transaction bank.—The differential mechanism which cooperates with the transaction keys is similar to that used 50 with the amount banks, except that the segments 211, and the differentially movable disks 212 and 213 are omitted and replaced by an arm 254 (Fig. 14) pivoted on the center 198. The arm 254 carries a latch 55 device identical with that described in connection with the amount differential mechanism. This latch device connects the arm 254 to a driving segment 255 of the same construction as the driving segment 60 209 associated with the amount bank.

The driving segment 255 for the transaction bank is driven by mechanism identically the same as that which drives the segment associated with the amount banks. 65 This mechanism includes the link 256, and

the lever 257 carrying rollers 258 and 259 cooperating with cams 260 and 261 fixed on the shaft 61. To the arm 254 is pivoted the usual beam 262 bifurcated to surround a pin 263 on a link 264 associated with the transaction bank. The beam 262 is operated in the usual way by a roller 265 wiping against the lower edge of said beam. The link 264 is connected, at its upper end to the indicator actuating mechanism, and at its lower end, to a stud 253 carried by an arm 266 secured to the shaft 250 which actuates a type carrier in the printing mechanism. The rocking of the shaft 250 also selects the classification totalizer for engagement with the amount actuating segments 211, all of which will hereinafter be described.

An arm 267 pivoted on the center 198 cooperates with the keys to disconnect the latch in the transaction bank.

The zero stop pawl in the transaction bank functions only to hold the detent 154 in its normal position and for this reason, the effective extension of the pawl in the transaction bank is left off, as shown in Fig. 14. A pin 268 on the pawl cooperates with an arm 269 pivotally supporting the lower end of the detent, and holds the detent in its raised position. It is always necessary to depress a transaction key to operate the machine. A bracket 270 (Figs. 13 and 14), fastened to the lower side of the transaction key frame, limits the movement of the differential mechanism in this bank so that the differential can never move past the "Cash" position (Fig. 1).

Totalizers

The machine illustrated has five totalizers, one for each of the transaction keys 152 and one for totalizing the items of each individual transaction. These totalizers, as mentioned in connection with the description of the differential mechanism, include 110 pinions 214, there being two sets of pinions 115 as illustrated in Figs. 19, 20 and 21. These totalizers are of the same type as illustrated in the patent to W. A. Chryst, No. 1,230,864, dated June 26, 1917, and the patents to F. L. Fuller, No. 1,242,170, dated October 9, 1917 and No. 1,394,256 dated October 18, 1921.

In Fig. 20 the classification totalizers together with their carrying frame are illustrated. As the frame is practically the same as that illustrated and described in the Fuller Patents 1,242,170 and 1,394,256, only a brief description will be given herein. Each set of totalizer pinions 214 is loose 125 on a tube 280 carried by arms 281 and 282 slidably mounted on a shaft 283. The upper ends of the arms 281 and 282 are slotted to engage blocks 284 secured to the hangers 120 and 196 thereby preventing said arms 125

from turning on the shaft 283 and also guiding the totalizer pinions into mesh with the actuating segments. Connecting the arms 281 and 282 is a shaft 285 which spaces the two arms the proper distance apart. The two arms, the shaft 285 and tube 280 form a frame slideable on the shaft 283 for bringing any desired pinion 214 into operative relation with the differential segments 211, as is old and well known in the art, and described in the Fuller Patents Nos. 1,242,170 and 1,394,256.

The totalizer frame, with its four totalizers, is moved laterally by the differential mechanism under the control of the transaction keys 152 which control the rocking of the shaft 250 (Fig. 14), as previously described. Secured to the shaft 250 is a spiral gear segment 286 meshing with a spiral gear 287 secured to a sleeve 288 freely mounted on a rod 289 supported by a bracket 290 (Fig. 12). There is also secured to the sleeve 288 a partial gear 291 which meshes with teeth 292 formed on the lower edge of a sliding plate 293 guided by pins 294 fastened in the bracket 290. The upper edge of the plate 293 is provided with a slot 295 receiving the lower end 296 of the arm 282, which is a part of the totalizer frame, as previously described. By this mechanism the totalizers are moved laterally into positions determined by the transaction key.

The various groups of totalizer wheels 214 are retained in their lateral positions by spacing collars 297. These wheels are prevented from rotating, when in normal position, by an alining bar 298 pivotally supported on levers 299 fulcrumed on the rod 285 and held in lateral position on the rod 40 by collars 300.

The shaft 283 (Figs. 5 and 20) has freely mounted, on each end, rollers 305 guided in slots 306 formed in cam plates 307, one secured to each of the side frames 308 and 45 309. Fastened near the ends of the shaft 283 are arms 310 carrying rollers 311 extending into cam slots 312 formed in the cam plates 307. Pivoted to the right hand arm 310 is a link 313 moved, by means to be hereinafter described to rock the shaft 283 counter-clockwise, as viewed in Fig. 5. This movement of the shaft 283, through the engagement of the roller 311 with the cam slot 312, causes the shaft 283 and arms 281 55 and 282, carrying the totalizer pinions 214, to be moved toward the center of the machine to engage the pinions 214 with the differential segments 211. This engagement takes place, in adding operations, after the 60 differential segments have been positioned under the control of the depressed amount keys 110. When the segments are restored to normal positions the amount which was placed thereupon is accumulated upon the 65 totalizer pinions, after which the link 313

is again moved to disengage said pinions from the differential segments.

When the shaft 283 (Fig. 14) is rocked counter-clockwise to engage the pinions with the differential segments, a pawl 314 fastened to said shaft contacts a shoulder 315 on the lever 299 and rocks the lever counter-clockwise, which withdraws the alining bar 298 from the pinions, allowing the selected pinions to be rotated. The remaining pinions are held against rotation by the lugs 284 (Fig. 20) on the hangers 195 and 196. When the totalizers are moved out of engagement from the actuating segments 211, the pawl 314 strikes an edge 316 of the lever 299 and rocks said lever clockwise to normal position, thereby moving the alining bar 298 between the teeth of the totalizer pinions 214 to hold them against rotation.

Secured to, and rocking with the shaft 283, is a totalizer aliner arm 317 (Figs. 20, 22 and 23) which cooperates with a slotted aliner 318 fastened to the shaft 285, and moving laterally with the totalizer pinions, to hold the selected pinions in lateral alinement with the differential segments.

The transaction totalizer line is shown in Fig. 21. It occupies a position to the rear of the differential mechanism in Fig. 19 and is of practically the same construction and has the same operation as the other totalizer line heretofore described, except that it includes but one set of totalizer wheels always in alinement with the differential segments 211. The totalizer frame is held in lateral position by collars 319 fastened to the shaft 320. The wheels of this totalizer are returned to zero position after totalizing a transaction, all of which will hereinafter be described.

Totalizers—Engaging controlling mechanism.—From the above description it can be seen how the totalizer lines are rocked into engagement with the differential segments 211. When the machine is operated, in registering the items of a transaction, both lines of totalizers are rocked into engagement with the differential mechanism simultaneously. When totalizing the items of a transaction, the single totalizer line only, is 105 rocked into engagement with the differential mechanism, and when taking a subtotal, or grand total, from any one of the four classification totalizers, this line of totalizers only, is moved into engagement 110 with the differential mechanism.

After the classification totalizer line has been shifted to position a totalizer to be operated by the differential segments 211, the selected totalizer pinions 214 are rocked 115 into mesh with said segments. Loose on a hub 326 (Fig. 6) is a three-armed lever 327. Associated with each of the arms 328 of said lever is a bell crank 329 pivoted on a stud 330 secured in a frame 331. Pivoted on a 120

stud 332 of the bell crank 329 is a lever 333 having a slot 334 into which projects a pin 335 carried by the previously described link 313. Pivoted on the stud 332 of the bell crank 329 associated with the "back" totalizer is a link 336 carrying a pin 337 embraced by a hook 338 of a lever 339 pivoted on a stud 340 secured in the frame 331. The lever 339 has a roller 341 projecting into a cam race 342 of a disk 343 fastened to the shaft 61. The configuration of the cam race 342 is such that, during the clockwise rotation of the disk 343, the lever 339 is rocked counter-clockwise, thereby lowering the link 336 and rocking the lowermost bell crank 329 clockwise. Through the connection of this bell crank with arm 328, the three-armed lever 327 is rocked counter-clockwise, thereby rocking the other bell cranks 329 clockwise. This rocks the levers 333 counter-clockwise with the pins 334 as the fulcrum points, which, through the pins 335, rock the links 313 clockwise about the stud 331, until pins 347 on said links 313 contact the wall 1358 of slots 358 in the frame 331, whereupon the levers 333 rock counter-clockwise with the pins 335 as the fulcrum points. This last movement of the levers 333 moves the pins 344 out of contact with a totalizer selecting disk 350 to permit free adjustment of the disks 350. When the pins 347 are against the walls 1358, these pins are withdrawn from the hooks 348 formed in a plate 349 (Fig. 5).

85 Each pin 344 in the lever 333 (Fig. 6) projects into the plane of the totalizer selecting disk 350 loose on the hub 326. The pins 344 are normally held in contact with the disk 350 by a spring 351. The disk 350 has pivoted thereto a link 352 also pivoted to an arm 353 fastened to a shaft 354 journaled in the side frames of the machine. This shaft is rocked by the link 264 (Fig. 14), heretofore described.

86 The selecting disk 350, link 352 and arm 353 (Fig. 6) are used in certain machines, such as the ones referred to in the patents above noted, to select the totalizer lines to be actuated in registering items, but in this particular machine both totalizer lines are always actuated when registering items, and therefore, the various parts shown for selecting totalizer lines are shown as standard construction.

87 When the lever 339 is rocked clockwise to normal position the bell cranks 329 are rocked counter-clockwise to normal positions. This movement of the levers 329 rocks the levers 333 clockwise with the pin 335 as the pivot points, as above described. However, with the disk 350 in the position shown, the pins 344 strike the outer periphery of the disk 350, thereby causing the levers 333 to be rocked clockwise with the pins 344 as the fulcrums.

This clockwise movement of the levers 333, through their engagement with the pins 335, rocks the links 313 counter-clockwise and engages the pins 347, which project through slots 358 (Fig. 6) in the frame 331, with the hooks 348 on the spider 349 (Fig. 5). Said spider carries a stud 359 entering a notch 360 of a link 361 pivoted at 362 to a lever 363 mounted on a stud 364 in the frame 308. The lever 363 carries anti-friction rollers 365 and 366 which cooperate with cams 367 and 368 respectively, fast on the shaft 61.

Clockwise movement of the cams 367 and 368, through the rollers 365 and 366, rocks the lever 363 first clockwise and then counter-clockwise to normal position. The clockwise movement of the lever 363 moves the link 361 to the right, thereby rocking the spider 349 clockwise. As the pins 347 (Fig. 6) are engaged by the hooks 348 (Fig. 5) it can be clearly seen that the pins will be moved in the long portion of the slots 358 (Fig. 6) whereby, through the links 313, the arms 310 (Fig. 5) are rocked counter-clockwise, and the rollers 311 on the arms 310, are moved in the slots 312 of the cam plates 307 and, as previously described, move the totalizer pinions 214 (Fig. 18) into engagement with the differential segments 211. When the lever 363 is rocked counter-clockwise to normal position the link 361 is moved to the left, thereby reversing the movement of the spider 349 and moving the studs 347 and consequently the links 313 to the positions shown.

With the disk 350 (Fig. 6) in the "0" or any other position it is clear that both totalizer lines are rocked into engagement with the differential segments.

Indicators.—The indicating mechanism disclosed in connection with the present machine is substantially the same as that fully illustrated and described in United States Letters Patent 1,163,748, issued to F. L. Fuller December 14, 1915. Therefore, but a brief description of it will be given herein.

There are two groups of indicators 375 (Figs. 1 and 19) for each of the amount banks of keys 110. One group of indicators 375 indicates at the front of the machine and the other group indicates at the back of the machine. There are likewise two groups of indicators 376 associated with the transaction keys 152.

As all of these indicators are similarly mounted, the group, associated with one of the amount banks only is illustrated and will be described.

The groups of indicators 375 are carried in a carriage 377 and rest upon ledges 378 of a runner 379 slidably mounted on rollers 380 on rods 381 supported by two frames 382, one at each end of the machine. The frames 382 are secured to the frames 308 130

and 309 by screws 383. The runner 379 has teeth 384 meshing with a segment 385 integral with the previously described segment 246 differentially positioned through the link 245 by the differential mechanism. In this manner, the carriage 377, carrying the groups of indicators, is differentially positioned to bring any desired indicator 375 into operative relation with an indicator 10 lifting means to be hereinafter described.

As the indication from the back of the machine is the reverse of that looking from the front, all the various groups of front and back indicators cannot be mounted on 15 runners similar to runner 379, but must be carried by separate runners and the back indicators differentially positioned from the segment 385, which operates the front indicators, by sleeves 386 which carry a second segment similar to segment 385 in mesh with a rack formed in the back indicator runner.

Indicators—Lifting mechanism.—The indicator lifting mechanism is substantially 20 the same as that shown and described in the above mentioned Fuller Patent 1,163,148. After the indicator carriages have been differentially positioned according to the keys depressed, the selected indicators are exposed to view by a frame 387 having projections 388 at the front and back thereof, and adapted to raise the selected indicators to view. Before the carriages 377 are differentially positioned, the indicators exposed during the previous operation are lowered to their normal positions by lowering the frame 387.

Indicators—Alining mechanism.—Each of the segments 246 has alining notches 389 with which cooperates an alining bar 390 integral with parallel arms 391 and 392 pinned on a shaft 393. Secured to this shaft and outside of the right hand side frame is an arm 394 (Fig. 2) pivoted to a link 395. The lower end of the link is pivoted to an arm 396 freely mounted upon a stud 397 projecting from the side frame of the machine. This arm carries rollers 398 and 399 (Fig. 4) cooperating with cams 400 and 401 respectively, secured to the shaft 61. As the shaft 61 rotates in a clockwise direction the cams move the arm 396 first counter-clockwise to withdraw the alining bar 390 from the segments 246 so that they may be differentially positioned under the control of the differential mechanism, and then clockwise to again engage the bar with the segments to hold them in proper positions until a subsequent operation of the machine.

60 There is also another alining mechanism which directly alines the runners 379 of the indicator carriage. This aliner 402 is in the form of an angleiron (Fig. 19). In alinement with each runner 379 the aliner 402 has a slot which guides the runner in its

movements and also an alining tooth 403 which cooperates with teeth 404 formed in the runner 379. The aliner 402 is secured at each end to the horizontal portion of an arm 405 pivoted on studs 406 mounted in the plates 382. Pivoted to the arms 405 are links 407 pivoted to arms (not shown) secured to the shaft 393 which causes the two alining members to operate in unison.

Special counters.—The machine illustrated 75 has six special counters (Fig. 10), one for each of the transaction keys 152 (Fig. 1), a customer counter and an item counter. These counters are of the same type as illustrated in the patent to Fuller, No. 1,394,256, 80 previously referred to. This special counter bank is located near the left hand side of the machine under the cover 411 (Fig. 1) and consists of a frame 412 (Fig. 10), supported at its upper and lower ends upon the tie rods 112 which support the key banks of the machine, as has been previously described. The special counters 413, 414 and 415 are of the usual rotation type, supported upon shafts 416 secured within the frame work 85 412. The wheels of the special counters are moved step by step by the usual graduated tined carrying pawls 417 (Figs. 7 and 8) to which are pivoted at 418, links 419 pivoted at 420 to slotted links 421 embracing pins 422 carried by the counter frame. The pivot 420 (Figs. 7, 8, 9 and 10) between each link 419 and 421 enters a slot 423 (Fig. 10), in an operating bar 424 pivoted, at its upper end, at the point 425 to a link 426 pivotally supported at 427 upon the frame 412, and at its lower end, at 428 to a bell crank 429 pivotally supported at 430 upon the counter frame. The bell crank 429 carries a pin 431 which fits within the bifurcated end of an arm 432 pivoted upon the tie rod 197 extending through the machine. The arm 432 which is bifurcated at 433 to receive a pin 436, carried by an arm 437 secured to a shaft 438 supported by the frames of the machine. This shaft is rocked only during a totalizing operation, by mechanism which will hereinafter be described. As the arm 437 moves in counter-clockwise direction it moves the arm 432 clockwise on its pivot against the tension of a spring 439 attached thereto and to the frame of the machine. As the arm 432 moves clockwise it moves the bell crank 429 counter-clockwise, which moves the bar 424 downwardly to operate 90

the customer counter 415 and one of the transaction counters 413 corresponding to the transaction key 152 depressed.

95 The transaction key, through the differential mechanism, controls the differential rocking motion of the shaft 354 (Fig. 14). This shaft has fastened to it an arm 445 (Fig. 10) connected by a link 446 to a lever 447 freely mounted on a stud 448 supported by the side frame of the machine. The 100

105 110 115 120 125 130

125

lever 447 is moved on its pivot in a counter-clockwise direction, raising the right hand or forward end 449 into position to cooperate with the transaction counter corresponding to the transaction key depressed. In this position the end 449 is in the plane of the link 421 (Fig. 7), and as the operating bar 424 (Fig. 10) moves downwardly the link 421 contacts the end 449 of the lever 447, and causes the toggle links 421—419 to straighten out thus moving the frame carrying the tined pawl 417 in a counter-clockwise direction to add "one" on the counter. The other transaction counters do not add at this time as the links 421, being unobstructed, move outwardly with 418 as their pivots, guided by the pins 422 in the elongated openings, and consequently the tined pawls 417 are not actuated.

The customer counter 415 adds "one" each time the machine is operated during totalizing transaction. Referring to Fig. 9, the elongated opening 450 in the link 421, associated with the customer counter, is shorter than the opening in the links of the transaction counters, and therefore, as the operating bar 424 moves downwardly the pivot point 418 moves to the right and operates the counter.

The item counter 414 adds "one" at each operation of the machine when registering items, but does not operate during a totalizing operation. As previously described, the depressing of the starting key 116 (Fig. 14) causes the shaft 79 to rock counter-clockwise, Fig. 10. Secured to the shaft 79, on the left hand end, is a bell crank lever 451 having a laterally projecting pin 452 upon which is freely mounted one end of a pitman 453. The forward end of this pitman contacts a pin 454 carried by a frame 455 which supports the tined pawl 417 associated with the item counter. A spring 456 returns the frame 455 to its normal position after each operation. The pitman 453 is guided in its movements by a slot 457 cooperating with a pin 458 carried in the upper end of a lever 459. This lever is fulcrumed on a stud 460 projecting from the side frame of the machine. In the lower end of the lever 459 is an angular slot 461 cooperating with a roller 462 carried on a stud mounted in a link 463 pivoted at a point 464 to an arm 465 fastened to the shaft 438. As this shaft is rocked counter-clockwise first by the totalizing lever 172, and afterward by the operation of the machine, as will be later described, the pin 462, carried by the link 463 and guided by a slot 466 in the side frame, moves in the formed slot 461 in the lever 459 causing said lever to swing counter-clockwise on its fulcrum 460, lowering the end of the pitman 453 away from the pin 454 so that, when the starting key is depressed, the item counter 414 will not oper-

ate on that operation of the machine. It is to be understood that the operating bar 424 associated with the special counters is given a movement only during a totalizing operation of the machine. Therefore, when the totalizing lever is set in the adding position only the item counter will add "one" at each operation of the machine.

The special counters are each provided with the usual re-set pawls actuated by a knurled knob 467 (Fig. 8) for setting the counter wheels to zero.

Cash drawer and bell.—With the totalizing lever 172 in the adding position, the cash drawer 473 (Figs. 41, 42 and 43) will not be operated and the bell 474 will not be sounded, during an operation of the machine. But with the totalizing lever in any one of the totalizing positions, the cash drawer will be operated and the bell will be sounded, during the operation of the machine.

The shaft 61, which rotates in clockwise direction at each operation of the machine, has secured to it an arm 475 having a laterally projecting pin 476 moving in the plane of an arm 477 fastened to a shaft 478 supported in the side frames of the machine. There is also secured to this shaft another arm 479 to which is attached a spring 480 to normally hold the arm 477 in contact with the shaft 61. With the totalizing lever 172 in the adding position, an operation of the machine will rock the shaft 478 without affecting either the cash drawer or the bell.

Moving the totalizing lever 172 to any of the totalizing positions gives a slight rocking motion to the shaft 438 in a clockwise direction. This motion is obtained by a slot 481 in the totalizing lever plate 166 (Fig. 11) cooperating with a pin 482 carried by a lever 483 (Fig. 6) freely mounted upon a stud 484 secured in the plate 331. Also mounted on the stud 484 is an arm 485 cooperating with the lever 483 to form a cam slot 486 into which a pin 487 projects. This pin is mounted in an arm 488 fastened to the shaft 438 (Fig. 5). The arm 485 (Fig. 6) is retained in its normal position, with a stud 491 thereon in contact with the upper end of the lever 483, a spring 489 attached to a pin 490 in the lever and the pin 491 in the arm. As the totalizing lever moves from the adding position in either direction the formed slot 481 (Fig. 11) causes the lever 483 (Fig. 6) to move counter-clockwise, which, with the cooperation of the arm 485, moves the arm 488 and shaft 438 (Fig. 5) clockwise through their initial movements.

Fastened to the shaft 438 (Fig. 43) is an arm 493, to which is pivoted a link 494. The lower end of the link has an elongated opening 495 into which a pin 496 (Fig. 41)

projecting laterally from an arm 497 fastened to a rock shaft 498 projects. The initial movement of the shaft 438 places the right hand end of the elongated opening 495 in contact with the pin 496. And as the machine is operated the shaft 498 is rocked counter-clockwise by a further movement of the link 494 by mechanism to be hereinafter described.

Secured to the shaft 498 is an arm 499 having a pin 500 projecting into a slot 501 formed in a sliding coupler 502 guided in its movements by studs 503 mounted in a drawer plunger lever 504 and extending into a slot 505 in the sliding coupler. As the arm 499 moves counter-clockwise the coupler 502 moves forward, placing the shoulder 506 in a position to be contacted by a projection 507 on the arm 479 secured to the shaft 478. With the coupler 502 in this forward position, the counter-clockwise movement of the shaft 478 will cause the drawer plunger lever 504 to swing in a like direction and lift a drawer plunger 508 to release the cash drawer 473.

The drawer plunger is mounted in a base 509 of the frame with a spring 510 entwined about the plunger between a pin 511 and the base. A collar 512 secured to the drawer plunger, above the base, controls the lower position of the plunger. In the upper end of the plunger is a vertical slot, in which the drawer plunger lever freely operates. A horizontal pin 514 secured in the plunger passes through an elongated opening 515 formed in the drawer plunger lever. The opening 515 in the drawer plunger lever is elongated to permit the plunger to rise, when closing the cash drawer, without moving the lever and also to allow a greater movement of the lever than that required to lift the plunger.

A spring 516 attached to a stud 517 mounted in the base and to the arm 497 moves the shaft 498 clockwise to return the coupler 502 to normal position.

As the plunger rises it is withdrawn from a bracket 518 fastened on the back of the cash drawer, allowing a spring 519 to move the drawer forwardly. As the drawer moves forwardly a bell crank lever 520 freely mounted upon the shaft 498 moves clockwise under the action of a spring 521 (Fig. 42) until an ear 523 formed on the lever 520 engages a shoulder 522 formed on the link 494 which has been moved forwardly during the operation of the machine. With the link 494 latched in its forward position the totalizing lever 172 cannot be returned to the adding position. This condition makes it necessary to return the cash drawer to its normal position, which moves the lever 520 counter-clockwise and moves the ear 523 from the path of the shoulder 522 on the link 494.

The drawer plunger lever, in addition to releasing the cash drawer, operates the bell mechanism. The forward end of this lever 504 has a formed ear 528 which normally contacts a pin 529 projecting laterally from a bracket 530 secured to the base 509. Freedly mounted upon a stud 531 secured in the bracket 530 is a bell hammer 532. In the normal position of the hammer a shoulder 533 thereon engages a pin 534 projecting laterally from the bracket 530. This hammer is retained in its normal position by a spring 535 attached to a pin 536 on the frame and to a trip pawl 537 freely mounted in a stud 538 secured in the bell hammer. The trip pawl 537 has a forwardly extending arm 539 normally in contact with a pin 540 on the hammer, and also an upright extending arm 541 in the plane of the ear 528 on the drawer plunger lever 504. As the drawer plunger lever moves counter-clockwise the ear 528 engages the arm 541 and causes the bell hammer to move clockwise on its pivot until the ear disengages from the arm, as the ear and arm rotate in opposite directions, at which time the bell hammer returns to normal position under the tension of the spring 535. A pin 542 mounted in the arm 479 contacts a projection 543 extending downwardly from the drawer plunger lever, and as the shaft 478 moves clockwise this lever is returned to normal position.

Printer.—The printing mechanism is located on the left hand side of the machine proper, and prints and issues a receipt 550 (Fig. 29) containing the date, consecutive number of the transaction, the amount of each item entered in the transaction, together with a total of the same, characters representing the class of transaction, the word "Total" and other selected data. In addition to the receipt, a record strip 551 (Fig. 28) is printed and retained within the machine, having a total of each transaction together with the classification character.

The nested sleeves 249 and shaft 250 (Figs. 19 and 40) actuated by arms 247 and 266 controlled by the differential mechanism, as previously described, support at their left hand ends segments 552 which mesh with teeth 553 of segment levers 554 freely mounted upon a stud 555 projecting laterally from the side frame 82. The upper ends of the segment levers 554 have teeth 556 in mesh with teeth 557 of partial gears 558 secured to nested sleeves 559 and a shaft 560 supported by the left hand frame 82 and a plate 561 (Fig. 24). Secured to the left hand end of the sleeves 559 and shaft 560 are item type printing wheels 562 and a transaction character wheel 563. Each type wheel has two sets of type characters to permit of impressions

being taken from the upper and lower sides of the wheels. The upper side prints upon the issuing receipt and the lower side upon the total record strip.

15 After the printing wheels are moved to their respective positions under the control of the differential mechanism they are retained in proper alinement, at the time of making the records, by an alining arm 564 (Fig. 40). This arm is loosely mounted upon a stud 565 secured in the printer frame 566. The forward end of the arm is bent at right angles to the arm, making a lip 567 which engages a notch 568 formed in the gear 558 as the arm 564 is moved counter-clockwise by a pin 569 carried by a lever 570.

20 The lever 570 (Fig. 34) which operates the alining arm is loosely mounted upon a stud 572 projecting laterally from the printer frame 566. Mounted on opposite sides of the lever are rollers 573 and 574 which cooperate with cams 575 and 576 respectively. These cams are secured to the 25 shaft 99 and at each operation of the machine give a reciprocating motion to the lever 570.

25 The issuing receipt 550 is fed from a supply roll 577 (Fig. 30), carried on a stud 578 supported in the printer frame, through a paper chute 579, between impression hammers and various type members and between a feed roller 580 and a tension roller 581 and past a severing plate 582. The paper 30 chute is supported by studs 583 and 584 secured to the printer frame. A spring-actuated arm 585 (see also Fig. 34), supported by the paper chute keeps the proper tension on the paper as it feeds through the chute.

35 The receipt feed roller 580 (Figs. 32 and 34) is loosely mounted upon a stud 586 supported at one end in the printer frame 566. Secured to the roller is a ratchet 587 engaged by a feed pawl 588 freely mounted on a stud 589 carried by an arm 590 loosely mounted upon the stud 586. The pawl is held in contact with the ratchet by a spring 591 and moves the feed roller clockwise to feed the receipt into its various printing 40 positions. A spring-actuated pawl 592 mounted on a stud 593 prevents a retrograde motion of the feed roller. Secured to the feed arm 590 (Fig. 34) and moving free on the stud 586 is a pinion 594 in mesh with a gear segment 595. This segment is loosely mounted on the type wheel sleeves 559 and has a rearwardly extending arm 596 provided with a stud to which the upper end of a link 597 is pivoted. The lower end of 45 the link 597 is pivoted on a stud 598, carried by a plate 599, pivotally mounted on a stud 600 projecting laterally from the printer frame 566. The plate 599 has an upwardly extending arm 601 to which is attached a spring 602 also attached to a pin

603 projecting from the printer frame 566. This spring normally keeps the stud on the extending arm 596 in contact with an edge 604 extending forwardly from the arm 570, and as this arm moves counter-clockwise 70 around its pivot the spring 602 causes the segment 595 to move clockwise and rotate the pinion 594 in a counter-clockwise direction, which moves the ratchet pawl 588 (Fig. 32) over the teeth of the ratchet. As the arm 570 moves clockwise to normal position the segment moves counter-clockwise to cause the ratchet pawl to move clockwise and rotate the feed roller 580. The movement of the feed roller, when printing items, 75 is equal to the spacing of items shown in Fig. 29 and is controlled by a pin 605 mounted in the segment 595. As the segment moves clockwise the pin engages the under side of a stop arm 606 (Figs. 34 and 80 35) and arrests the movement of the segment.

85 The printing of items requires a one-cycle operation of the machine, while the printing of the total of items requires a two-cycle operation, and during the first cycle of a two-cycle operation the receipt is given 90 in a short feed, and as the total is printed during the second cycle there will be a space 95 between the last item and the total, as shown in Fig. 29. After the total is printed the stop arm 606 is moved clockwise out of the path of the pin 605, which permits the spring 602 to give the plate 599 its full amount of movement, until the finger 607 100 on the plate strikes a stop 608 projecting from the printer frame. This full movement of the feed roller advances the issuing receipt to its severing position.

105 The stop arm 606 (Fig. 35) is loosely mounted on a sleeve 614 surrounding the stud 460 and is operated by a flexible driving member because of the overlapping of time in the operation of the different mechanisms that operate the segment and the 110 stop arm. The stop arm 606 has a laterally projecting pin 616 contacted by the spring actuated arms 617 and 618 held in contact with the pin by a spring 619. These flexible arms are driven by a pin 620 carried by 115 a lever 621 secured to the sleeve 614. Also fastened to this sleeve is an arm 622 (Fig. 40) with a formed slot 623 into which projects the roller 462, mounted on a stud carried by a link 463. The link is pivoted on a stud mounted in the arm 465 secured to the shaft 438. The roller 462 is guided in 120 a slot 466 (Fig. 10), in the side frame 82 (Fig. 24).

125 As previously described, the shaft 438 (Fig. 40) receives an initial movement when the totalizing lever is moved from the adding position to a totalizing position, and a second movement when the machine is operated with the totalizer lever in the last 130

mentioned position. As the machine is operated during the first cycle of operation, the pin 605 contacts the stop arm 606, thus limiting the movement of the segment 595.

5 As the sleeve 614 moves clockwise, the lug 627 (Fig. 35) contacts the left side of pin 605 and retains the stop arm in a partially operated position, whereas while the lever 621 continues its movement and expands 10 the spring 619. When the segment 595 moves counter-clockwise, near the end of the first cycle of operation to move the pin 605 out of the path of the stop arm, said stop arm is then permitted to complete its clockwise rotation, under influence of the spring 619. During the second cycle of operation, when the segment 595 moves clockwise, the stop arm is out of the path of the pin 605, to permit the receipt paper to be fed to the 20 severing position.

When it is desired to operate the machine without issuing a receipt the lower feed roller 581 (Fig. 32) is moved away from the upper feed roller 580. The lower roller is 25 loosely mounted on a rod 632 supported by a lever 633 and an arm 634 (Fig. 24) secured to the lever by a hub 635 and the rod 632 and forms a frame to carry the lower feed roller. This frame is loosely mounted 30 on a stud 636 projecting laterally from the printer frame 566. The lower roller is normally held in contact with the upper roller by a spring 637 attached to the lever 633 and to a pin 631 mounted in the frame.

25 Mounted in the lever 633 is a shouldered pin 638 which, as the lever is moved clockwise, is elevated above a shoulder 639 on a latch 640, pivoted on a stud 641. The latch 640 is moved counter-clockwise by a spring 642, and retains the lever 633 in position with the feed rolls out of contact with each other until the latch is released again by the operator.

The date is printed upon the issuing receipt by a month wheel 645 and two day wheels 646 (Figs. 37 and 38) mounted upon a shaft 647 supported by the frames 561 and 566. Secured to each date wheel is a gear 648 which meshes with a companion gear 649. 50 The gear 649, which operates the right hand date wheel, is fastened to a shaft 650 which has secured to its left hand end a setting knob 651. The middle date wheel operating gear 649 is secured to one end of a sleeve 652 surrounding the shaft 650 and has a setting knob 653 secured near its left hand end. The left hand date wheel driving gear 649 is secured to a second sleeve 654 with a setting knob 655 secured to the left hand end of said sleeve. The date wheels are retained 55 in their set positions by spring arms 656 secured to a rod 657 and engaging the driving gears 649.

The consecutive number is printed upon 60 the issuing receipt by a step-by-step coun-

ter, the wheels 660 of which are mounted upon the shaft 647 and carry type. They are operated by the well known tined pawl 661 carried by a yoked frame 662 journaled on the shaft 647. Fastened to the yoked frame 662 is an arm 663 (Figs. 32 and 37) having a stud 664 to which is loosely connected the upper end of a link 665. The lower end of said link is connected by a stud 666 to an arm 667 freely mounted on a shaft 668. Also freely mounted on the stud 666 is an arm 669 having a laterally projecting pin 670 in its lower end engaging the upper and lower sides of a notch 671 (Fig. 34), in the link 80 597 previously described. This arm is normally held in this position by a spring 672 (Fig. 32) entwined about the stud 666.

When a receipt is not issued it is necessary to preserve the consecutive number, and therefore, the operating mechanism must be disabled at this time. Connecting with the lower feed roller rod 632 is a bifurcated arm 673 of a plate 674 which oscillates on the nested tubes 559. A link 675 connects this plate with the arm 669 to move said arm counter-clockwise and withdraw the pin 670 from the notch 671 in the link 597 (Fig. 34).

The shaft 668 and arm 667 (Fig. 32) are not necessary elements in this particular machine, but when it is desired to print the consecutive number and date upon an inserted slip or the totalizing strip a duplicate mechanism of that shown in Fig. 37 is applied.

The consecutive number wheels are retained in position by spring actuated pawls 676 mounted on a rod 677 and engaging ratchet wheels secured to each number wheel.

The number wheels may be reset to zero position in the well known manner by a shaft 647 grooved to cooperate with spring-actuated pawls 678 carried on each wheel. This shaft is given a rotation in a clockwise direction by a knob 679 which is pulled to the left (Fig. 37) compressing a spring 680, until a slot 681 disengages from a pin 682 when the knob can be turned.

An electro plate for printing the word "Total" and the name of the merchant, as illustrated on the receipt (Fig. 29), is secured to a bar 686 (Figs. 32 and 34) supported by the printer frame 566 and cap 561.

There are three separate impression hammers for printing the issuing receipt. These hammers are all loosely mounted on a rod 687 supported by the printer frame 566 (Figs. 24 and 34). Also mounted on this rod is a frame consisting of a right hand arm 688 and a left hand arm 689 connected together so as to move as a unit, by tie rods 690 and 691. The right hand arm 688 has 130

an extension 692 carrying a laterally projecting pin 693 (Fig. 34 and 40) extending through the side frame to enter an elongated opening in a lever 694. This lever is 5 fulcrumed on a stud 695 and carries on its lower end a roller 696 contacting a cam 697 secured to the shaft 76 and rotating in a clockwise direction. The cam is made wide enough on the edge to engage both the roller 10 and the end of the lever. The roller rides on the cam until it leaves the highest point 698, when the lower end 699 of the lever rides the high part of the cam and has a sudden drop-off to give the desired blow to the 15 printing hammers. The roller and lever are held in contact with the cam by a spring 700 attached to an arm 701 projecting to the right of the lever and secured at its lower end to a pin 702.

20 As before mentioned, there are three printing hammers. The left-hand hammer 703 (Figs. 31 and 34), has a platen 710 and prints the items. The printer hammer 704 (Fig. 34) has four platens, one 659 for 25 printing the word "Total", one, 683 for printing the name of the merchant from the electro on the bar 686, and a third platen 684 (Fig. 31), which is narrow and extends over the amount type lines, but is only wide 30 enough to take impressions from the highest amount wheels. The fourth platen, 685, is for taking an impression from the transaction type wheel 563. The right-hand hammer 705 (Fig. 34) has a platen 724 and prints 35 the date and consecutive number. Individual springs 706 (Figs. 30 and 34), attached to the printing hammers and to the rods 691, normally hold the hammers 703 and 704 in contact with adjusting screws 40 708, and the hammer 705 in contact with a pin 709 projecting from the hammer 704.

It will be noted, by referring to Fig. 29, 45 that the word "Total" is printed at the bottom of the checks, and the name of the merchant at the top, whereas in the machine, the platens for printing this data are located side by side. The reason for this is, that the check is fed to bring the printed check to the severing knife 582 (Fig. 33), in such 50 position that the word "Total" is past the knife, but the part bearing the merchant's printed name and the consecutive number remains in the machine. Thus at the end 55 of the feeding and severing operation, the check paper remaining in the machine has printed thereon the merchant's name, consecutive number and the date, and the paper is in position to receive the first printed item.

60 The platen 710 (Fig. 24) mounted in the impression hammer 703 engages only four item type wheels which represent the registering capacity of the keyboard. The hammer 704 is recessed to permit the platen 710 65 to pass between the platens 684 and 685. In

registering items the hammer 703 is operated while the other hammers 704 and 705 are disabled. Secured to hammer 704 is a plate 711 having a laterally projecting pin 712 (Figs. 31 and 32) which, during the time 70 of registering items, is under a flange 713 (Figs. 31 and 35) formed in a plate 714 free to oscillate on the type wheel tubes 560. On the left hand side (Fig. 35) of this plate is a bifurcated projection 715 embracing a pin 716 carried by the lever 621, previously described.

When the totalizing lever is moved to either a sub-total or total position and the lever 621 operated, the plate 714 will be 80 moved counter-clockwise, carrying the flange 713 out of the path of the pin 712, which permits the impression hammers 704 and 705 to operate in cooperation with the hammer 703 to make an impression of all of the 85 type wheels 562 and 563, and also the date and consecutive number wheels and the electro plate.

The flange 713 (Fig. 35) is of sufficient length to remain in the path of the pin 712 90 during the initial movement of the arm 621. This initial movement also prevents the operation of the item hammer 703 during the first cycle of operation, when printing a sub-total or total, by moving a second flanged 95 plate 717 (Fig. 33), secured to the first flanged plate 714 by rivets 718, into the path of a pin 719 mounted in a plate 720 secured to the hammer 703. During the second cycle of operation the flanged plates 714 and 100 717 are given a further counter-clockwise movement which removes the flanges from the path of the pins 712 and 719 and permits all the printing hammers to operate.

The disabling of the receipt feed rollers 105 automatically disables the printing hammers. The plate 674 (Fig. 32) has a flange 721 which, as the plate moves counter-clockwise, will move over a shoulder 722 on the arm 711, and a shoulder 723 on the plate 110 720 (Fig. 33) and prevent the hammers from operating.

For the purpose of making a legible impression upon the issuing receipt 550 (Fig. 29) and also the total strip 551 (Fig. 28), 115 a continuous inking ribbon 730 (Fig. 34) is provided. This ribbon passes around guide rollers 731 supported by the printer frame and over an inking roller 732 mounted upon a stud 733 projecting from the printer frame. The inking ribbon is held taut by a tension roller 734 supported in a frame mounted upon a stud 735 projecting from the printer frame.

Secured to the inking roller is a ratchet wheel 736 (Fig. 36) actuated by a feed pawl 737 carried by an arm 738 freely mounted upon the stud 733 and held in contact with the ratchet wheel by a spring. A spring-actuated pawl 739 freely mounted upon the 120

stud 735 prevents a retrograde motion of the inking roller.

Secured to the arm 738 is a pinion 740 (Fig. 34) in mesh with a segment gear lever 741 fulcrumed on a rod 742. Pivoted to the segment lever by a stud 743 is a link 744 bifurcated at its lower end to engage a stud 745 mounted in the lever 570. A spring 746 is attached to the pitman 744 to move the segment lever 741 counter-clockwise when the lever 570 moves likewise. As the segment lever 741 moves counter-clockwise the carrying pawl arm 738 moves clockwise until a finger 747 (Fig. 36) on the arm contacts a shoulder 748 (Fig. 34) on a swinging frame 749 to control the feeding of the inking ribbon. When the seam 750 of the ribbon nears the impression point for the item printing wheels, the ribbon is given an extra amount of movement so as to pass the seam by this point. The swinging frame 749 is moved out of the path of the finger 747 by buttons 751 secured to the inking ribbon. These buttons are placed so as to move under the left hand arm 752 of the swinging frame and move it as the seam 750 approaches either the upper or the lower impression points.

The total record strip 551 retained in the machine is fed from a supply roll 756 (Fig. 30 and 34) around guide studs 757 and onto a receiving roll 758 rotated in a counter-clockwise direction (Fig. 34) by a spring-pressed pawl 759 carried on a bell crank lever 760, oscillated by the plate 599 through a link 761. A spring-pressed pawl 762 mounted on a stud 763 prevents retrograde motion of the receiving roll.

The pawl 759 (Fig. 24), is effective to feed the total record strip 551 only during the second cycle of a total printing operation. The arm 760, carrying the feed pawl 759, is connected to the lever 599 by a link 761 (Figs. 30 and 34), and the lever 599 is connected to the receipt feed segment 595 by the link 597 so that any movement given the receipt feed segment 595 is transmitted to the total record strip feed arm 760.

As hereinbefore mentioned, the receipt is given a short feed during adding operations and is given both a short feed and a long feed during total-taking operations. The feed arm 760 is not rocked as far during short feed operations of the segment 595, as during long feed operations. When the arm 760 receives such lesser extent of movement during adding operations and during the first cycle of a total-taking operation, the pawl 579 slides idly back and forth on its ratchet disk, such movement being insufficient to move the pawl to engage the next tooth of the ratchet. Therefore, during adding operations and during the first cycle of a total-taking operation the total record strip is not fed.

However, when the receipt feed segment 595 is given a longer extent of movement during the second cycle of a total-taking operation to give the receipt a long feed, the arm 760 rocks clockwise far enough to permit the pawl 759 to drop behind the next tooth of the ratchet so that upon counter-clockwise movement of the arm 760 the pawl 759 catches behind a tooth on the feed ratchet to feed the record strip 551 one step to space the printed total from the last printed item, as illustrated in Fig. 29.

The impression is made upon the total record strip by a hammer 764 carrying an impression platen 765 and loosely mounted on the stud 572 (Fig. 30). This hammer has a rearwardly extending arm 766 contacting an adjusting screw 767 mounted in a cross bar of a swinging frame 768. A spring 769 normally holds the impression hammer in contact with the adjusting screw and causes the hammer to move clockwise with the frame 768 during a total operation. A spring 770 attached to a pin secured in the side frame and to the swinging frame, maintains a roller 771, carried by the frame, and a toe 772, formed on the right hand member of the frame in contact with a cam 773 fastened to the shaft 99. The edge of the cam is of sufficient width to contact both the roller 771 and toe 772 on the frame so that when the roller leaves the node 774 of the cam the toe 772 will hold the hammer in its lower position until the node of said cam moves away from the toe 772, when the hammer quickly returns upwardly under the action of the spring 770 causing the platen to strike the type wheels, the hammer then being retracted to its normal position by the spring 769.

As the total hammer operates only during the printing of totals, this hammer is disabled, when recording items, by a pin 776 on a plate 775 (Figs. 31 and 34) and a cooperating flange 777 on the plate 714 previously described. With the hammer in disabled position the swinging frame 768 moves at each operation of the machine, stretching the spring 769 without moving the hammer, as is also done with the receipt printing hammers when they are disabled.

Total and sub-total mechanism

Referring to Fig. 2 the lever 172, when moved into a total or sub-total position, controls mechanism to prevent the restoring of the motor locking lever 70 (Fig. 26) to normal locking position until near the end of the second rotation of the shaft 61.

Slidably mounted on the stud 59 (Figs. 2 and 3), is a link 785 one end of which is pivoted to a lever 786 loose on the stud 184. Pivoted to the lever 786 is a link 787, also pivoted to an arm 788 secured to the previously mentioned shaft 438. The link 785

has a stud 789 engaging a slot 790 in the previously described link 147. The link 785 has two pins 791, one on each side of a flange 792 of a coupling bar 793 slidably mounted in a groove 794 in a disk 795. The link 785 also has an anti-friction roller 796 normally in engagement with a notch 797 in the disk 795 mounted on the stud 59. The gear 58 has a circular cut 798 in which the disk 795 is located.

From previous descriptions it will be remembered that the movement of the total lever 172 either up or down for a sub-total or total operation, respectively, rocks the lever 15 483 and arm 485 (Fig. 6) counter-clockwise through the engagement of the pin 482 with the slot 481 (Fig. 11) in the plate 166. This movement, through the pin 487 (Fig. 5) rocks the arm 488 and the shaft 438 clockwise. Clockwise movement of the shaft 438 (Fig. 2) rocks the arm 788 clockwise, whereby through the link 787, the lever 786 is rocked clockwise and moves the link 785 to the left in the direction of its length. The link 785, through the engagement of its pins 791 with the flange 792 of the coupling bar 793, moves said coupling bar to the left into a notch 784 in the gear 58, thus connecting said gear with the disk 795. At the same time the roller 796 is moved into a cam slot 800 in the disk 795. The link 785 also rocks the link 147 clockwise about the stud 145. As the disk 795 is connected to the gear 58, the counter-clockwise movement of said gear 35 and disk, through the cam roll 796, moves the link 785 still farther to the left and rocks the link 147 still farther, so that when the lever 183 is lowered, near the end of the first half rotation of the gear 58 by the cam 40 181, as described in adding operations, the stud 185 moves idly in the elongated portion of the opening 186, thus preventing the link 147 from rocking the shaft 79 to return the various parts to normal positions, 45 thereby permitting the motor clutch to drive the gears and shaft 61 a second rotation. Near the end of the complete rotation of the gear 58 the link 785 is moved to the position in which it was adjusted by the total 50 lever 172 so that when the lever 183 is rocked clockwise the second time by the second cam 801 the stud 185 engages a shoulder 802 in the opening 186 to lower the link 147 to rock the lever 144 and shaft 79 counter-clockwise 55 (Fig. 2) slightly past normal position, but not as far past normal as in adding operations. Just before the end of the second operation, the lever 70 (Fig. 26) is rocked to normal position to stop the motor, as in 60 adding operations. The shaft 79 is rocked slightly past normal position so that the stud 133 (Figs. 15 and 17) is carried to the rear of the non-repeat pawl 136 and said pawl is rocked clockwise by a spring 137 to prevent 65 an immediate second operation of the ma-

chine when the total lever is out of its adding position. With the non-repeat pawl 136 in front of the stud 133, when the total lever is out of adding position, the spring 163 moves the release bar 120 and rocks the release pawl 132 clockwise (Fig. 17) to normal position, whereby it moves the non-repeat pawl 136 out from in front of the stud 133 and the spring 148 (Fig. 2) rocks the shaft 79 and arm 139 (Fig. 14) to normal positions. In adding operations the shaft 79 is rocked farther past normal position than in total and sub-total operations, to release the operated amount keys, but during total and sub-total operations the detents 114 are locked against operation by a rod 846 (Fig. 19), moved into contact with the lever 848, and therefore, the shaft 79 cannot be rocked as far during total and sub-total operations, as during adding operations. If the shaft 79 were rocked far enough to lower the detent, as during adding operations, a serious interference would result, since the detents 114 are held against movement by the universal rod 846. The mechanism for rocking the universal rod 846 into locking position will be described later.

In totalizing operations a selected totalizer is moved into engagement with the gear segments 211 before said segments are moved by the driving segments 209 and latches 215, whereby the differential movement of the gear segments 211 is controlled by the totalizer pinions 214. After the actuators have been moved differentially under the control of said totalizer, the totalizer is disengaged from the actuator thereby leaving the totalizer at zero.

In sub-totalizing operations the totalizer is engaged with the actuators before the actuators are moved differentially, and held in engagement with said actuators to control the differential movement thereof to print a sub-total. The totalizer is also held in engagement with the actuators while said actuators are being restored, thereby accumulating upon the totalizer the amount which was taken therefrom. The mechanism for controlling the engaging and disengaging of the totalizer in the total and sub-total operations will be hereinafter described.

The mechanism whereby said totalizer controls the differential movement of the actuators during total and sub-total operations will now be described. Pivoted on a stud 810 (Fig. 11) on a hanger 811 is a lever 812 carrying a pin 813 projecting into a slot 814 in the total lever plate 166. The lever 812 has a slot 815 into which projects a pin 816 on a link 817. The pin 816 normally lies within a notch 821 in the stationary hanger 811. The link 817 is pivoted to an arm 819 secured to a shaft 820. There are two levers 812 and two of each

of the other elements just described. One set of elements is adapted to cooperate with each one of the sets of totalizers, there being two sets of totalizers in the machine shown. The slots 814 are both of different shapes. When the total lever 172 is moved to the first position below the adding position the arm 812 associated with the rear or transaction totalizer is rocked counter-clockwise, whereby the pin 816 is withdrawn from a notch 821 and moved into a notch 822 in a notched disk 823 secured to the previously described hub 326. When the total lever 172 is moved to the second position below adding position, or to the position above the adding position, the lever 812 associated with the forward or classification totalizers is rocked counter-clockwise to withdraw its pin 816 from the notch in the hanger 811 and cause it to be moved into the notch 822 in the notched disk 823.

As previously described, in adding operations the spider 349 (Fig. 5) is rocked first clockwise and then counter-clockwise to engage the selected totalizer with, and disengage it from, the actuator. The hub 326, as previously described, is secured to the spider 349, and therefore, when said spider is rocked the notched disk 823 is rocked first clockwise and then counter-clockwise (Fig. 11).

For illustrative purposes, let it be assumed that the total lever 172 has been moved downwardly to the transaction totalizing position, which is the first position below the adding position. Movement of the lever 172 to this position withdraws the pin 816 from the stationary slot 821 and moves it into the notch 822 in the disk 823. After this has taken place, and during the operation of the machine, the disk 823 is rocked first clockwise and then counter-clockwise to normal position. The clockwise movement of the disk 823, moves the rear link 817 (Fig. 11) downwardly, thereby rocking the shaft 820 counter-clockwise. Secured to the shaft 820 is a partial gear 824 (Fig. 18) meshing with a segment 825 loose on a stud 826 on the plate 196. The segment has an integral arm 827 having a slot embracing a stud 828 on a link 829 pivoted to a lever 830 loose on the stud 826. The lower end 831 of the lever 830 is in the plane of the gear segment and totalizer pinion 214. Pivoted to the stud 828 is a link 832 also pivoted on a stud 833 of a lever 834 pivoted on a stud 835 on the plate 196.

Counter-clockwise movement of the shaft 820 rocks the segment 825 clockwise, and through the connection of the slot in the arm 827 with the stud 828, the link 829 is rocked slightly clockwise about the stud 826. At the same time the lever 830 is rocked clockwise about the stud 826, to position the lower end 831 of the lever so that as the

pinion 824 is rotated counter-clockwise the long tooth 836 of said pinion strikes the lever 831. The clockwise movement of the segment 825 and arm 827 also rocks the link 832 counter-clockwise about the stud 833 and positions the links 829 and 832 so that they are in a straight line.

After this has taken place the totalizer pinion 214 is engaged with the segment 211 in a manner to be hereinafter described, and the driving segment 209 (Fig. 19) is rocked counter-clockwise, the same as in adding operations, and through its connection with the latch 215, the disks 212 and 213 and actuating segments 211 are rotated clockwise (Fig. 18), thereby causing a counter-clockwise rotation of the pinion 214.

During this rotation of the pinion, the long tooth 836 thereof strikes the lower end 831 of the lever and rocks it counter-clockwise. The plate 823 (Fig. 11) reaches the limit of its clockwise movement before the lever 830 (Fig. 18) is rocked counter-clockwise, as just described, thereby holding the shaft 820, gear 824 and segment 825 in the positions into which they have been moved by the plates 823.

With the parts moved to the positions as just described, the counter-clockwise movement of the lever 830 lowers the link 829. As the link 832 is in a straight line with the link 829, movement of the link 829 moves the link 832 towards the left in Fig. 18, and the stud 828 slides in the slot in the arm 827. The link 832 thus rocks the lever 834 clockwise, carrying a flattened stud 837 thereon into one of the notches 838 in the previously described reset spider 230, which it will be remembered is connected to the pin 232 on the latch arm 224. When this occurs the reset spider 230 is stopped in a position commensurate with the amount upon the totalizer pinion 214. The stopping of the reset spider 230 in this manner causes the latch 215 to be disengaged from the driving segment 209, thereby stopping the differential segment 211 in a position commensurate with the value upon the totalizer pinion 214. After the segment 211 has been positioned under the control of the totalizer pinion the beam 241 is actuated in identically the same manner, as during the adding operations, to set up the type wheel to print the amount taken from the totalizer pinion.

After the beam has been set, the totalizer is disengaged from the segment 211, thereby leaving said totalizer in its zero position. When the totalizer is disengaged a spring 839 rocks the lever 834 counter-clockwise to normal position, thereby disengaging the stud 837 from the plate 230.

The disk 823 is then rocked counter-clockwise (Fig. 11) to normal position, whereby the shaft 820 and partial gear 824 (Fig. 18) are rocked clockwise and rock the segment 211

825 counter-clockwise to normal position, thereby lowering the link 829 and rocking the lever 830 counter-clockwise to normal position. This movement of the segment 825 5 also rocks the link 832 clockwise about the stud 833 to normal position.

Should the totalizer be in the zero position when it is rocked into engagement with the segment 211, the long tooth 836 immediately 10 strikes the end 831 of the lever 830. When this occurs the clockwise movement of the segment 825, through the engagement of its arm 827 with the stud 828, straightens out the links 829 and 832 and immediately rocks 15 the lever 834 clockwise, whereby the stud 837 enters the notch 838 in the zero position. Consequently the latch is disconnected at zero and the segment 211 is not moved beyond zero position.

20 *Total and sub-total-Interlock.*—Means are provided for preventing depression of amount keys when the total lever is out of adding position. As there are no amount keys depressed it is also necessary to render 25 the zero stop pawl 115 ineffective in order that the differential mechanism may be controlled by the long tooth 836 of the totalizer pinion 214, as above described.

As above stated, when the total lever 172 30 is moved either above or below its adding position the shaft 438 is rocked clockwise (Fig. 5) or counter-clockwise, as viewed in Fig. 19. This shaft has secured thereto a pair of arms 845 (only one of which is shown 35 in Fig. 19) carrying a rod 846. Counter-clockwise movement of the shaft 438 and arms 845 moves the rod 846 (see also Fig. 24) downwardly in front of a foot 847 integral with an arm 848, moved counter-clockwise by the depression of any of the keys 40 110. With the rod 846 in front of the lower end of the arm 848 it is very clear that said arm cannot be rocked counter-clockwise, therefore, none of the keys 110 can be depressed.

If an amount key is depressed, the total lever 172 can be moved by forcing it, but this movement positions a bell crank 849 (Fig. 6) in front of the stud 189 and prevents the machine from being released, as 45 previously described. With an amount key 110 depressed, the arm 848 (Fig. 19) is rocked counter-clockwise and its lower end is moved beneath the rod 846, but there is 50 enough clearance between said arm and said rod to allow the rocking of the bell crank 849 (Fig. 6) to position it in front of the stud 189. When this clearance is taken up, the continued forcing of the lever 172 expands 55 the spring 489 so that the mechanism will not be strained. To release the machine for operation the total lever must be moved to its adding position and the keys 110 released by partially depressing another 60 key in the same row.

As previously described, the shaft 438 is rocked further counter-clockwise by the mechanism illustrated in Fig. 2, whereupon the rod 846 (Fig. 19) engages the lower end 70 of the zero stop pawls 115 associated with each of the amount banks and rocks said pawls clockwise so that their upper ends cannot disengage the latches at zero.

Total and sub-total totalizer engaging control 75

As described in connection with the adding operation, the selecting plate 350 (Fig. 6) controls the totalizer engaging mechanism so that in all adding operations two 80 totalizers are engaged with the actuators. However, in total and sub-total operations only one totalizer line can be rocked into engagement with the actuators at a time. Therefore, it is necessary to render the totalizer engaging controlling mechanism, which 85 operates in adding operations, ineffective and to select the totalizer line and control its engaging and disengaging with the differential mechanism by the total lever 172. 90 When the total lever 172 is moved downwardly to the first one of its two lower positions the "Transaction" totalizer is rocked into engagement with the actuators to have the total taken therefrom. When the total lever is moved further downwardly to the second one of its lower positions the "Classification" totalizer is rocked into engagement with the actuators to have the total taken therefrom. When the total lever 100 is moved upwardly to the upper position the "Classification" totalizer is rocked into engagement with the actuators to have the sub-total taken therefrom.

As previously described, in adding operations the link 361 (Fig. 5) is moved toward the right and through its connection with the stud 359 rocks the spider 349 clockwise to engage the selected totalizer with the actuators after the actuators have been differentially positioned under the control of the amount keys 110. After the actuators have been returned to normal, the link 361 is moved to the left to normal position and disengages the totalizer from the actuators. In 110 total and sub-total operations the time of engaging and disengaging the totalizers is entirely different from that described in adding operations.

The total lever plate 166 has a slot 852 115 (Fig. 11) into which projects a pin 853 supported by one of the levers 329 (Fig. 6). The slot 852 has a notch 854 within which the pin 853 moves idly when the lever 329 is rocked clockwise during adding operations. When the lever 172 is moved into position for total or sub-total operations the slot 852 and pin 853 rock the lever 329 clockwise and move all of the levers 333 far enough to move the pins 344 120 125

away from the outer periphery of the plate 350. When the pin 853 rocks the one lever 329 the other two are rocked by the three-armed lever 328. Any subsequent movement 5 of the plate 350 has no effect upon the levers 333 or links 817 for engaging the totalizers with the differential actuators, as would be the case during adding or listing operations.

It has been previously described that a 10 movement of the total lever 172 into position for taking totals or sub-totals causes a movement of the lever 483 (Fig. 6) in a counter-clockwise direction. Pivoted to the lever 483 is a link 855 also connected to the 15 stud 337 normally embraced by the hook 338 of the lever 339. Counter-clockwise movement of the lever 483 moves the link 855 to the right, thereby disconnecting the stud 337 from the lever 339 and rocking the 20 link 336 counter-clockwise about the stud 332. It will be remembered that the lever 339 is actuated by the cam 343, during adding operations, to move the link 336 and rock all the levers 329 to actuate the pins 344 25 to cause the totalizers to be meshed with the differential actuators. By disconnecting the link 336 from the lever 339 the driving connection between the cam 343 and the levers 329 is broken.

30 Since the operation, or the condition set up by the total lever 172 as just described, has crippled the automatic means for causing the totalizers to be meshed with the differential actuators, means are provided for 35 setting up a condition by the total lever itself for determining, during totalizing operations, which totalizer is to be meshed with the differential actuators. The total lever plate 166 has two irregularly shaped 40 slots 345 (Fig. 11), each slot receiving one of the pins 344 on the levers 333 (Fig. 6). These slots are so shaped that when the total lever 172 is moved downwardly to total or 45 reset positions, the pins 344 are moved radially away from a rod 856. Since the levers 329 are held stationary after being rocked clockwise by the total lever, the movement of the pins 344 causes a clockwise movement of the levers 333 around the stud 332 and by 50 the connection of said levers and the links 313 said links are moved outwardly and position the pins 347 within the hooks 348 of the spider 349. When said spider is rocked clockwise, as previously described, the links 55 313 rock the totalizers associated therewith into mesh with the differential actuators. Each of the slots 345 has a different shape so that the pins 344 are moved alternately, whereby their associated pins 347 are moved 60 alternately within the hooks 348. In other words, only one of the pins 347 can be moved into a hook 348 at any one time during totalizing operations.

This same condition is true when the total 65 lever 172 is moved upwardly to its sub-total

or reading position, as the slots 345 have the same shapes on each side of the position where the pins 344 normally enter said slots.

From the above it can be seen that only one totalizer line can be selected, during a total or sub-total operation, to be rocked into engagement with the actuators. The previously described slots 814 are also of different shapes so that if, for instance, the lower pin 347 is moved to engage its hook 348 the lower slot 814 moves its pin 813 and rocks the back shaft to move the lower end 831 of the lever 830 (Fig. 18) associated with the back or transaction totalizer into position to be acted upon by the long tooth 836 of the back totalizer.

In totalizing operations the link 361 is moved to a different position from that shown in Fig. 5. This is done by the total lever 172 preliminary to an operation of the cam shaft 61, so that the time of the engaging and disengaging totalizers may be changed in accordance with the desired operation. When the total lever 172 is moved counter-clockwise for a totalizing operation 90 a slot 857 therein through its connection with a pin 858 on a lever 859 (Fig. 5), pivoted on a stud 860 on the plate 331, rocks said lever 859 clockwise. At the same time the lever 483 (Fig. 6) is rocked counter-clockwise by the slot 481. Pivoted at 861 to the arm 488 is a link 862 which carries a stud 863 extending into a slot 864 in the lever 859 and in the straight portion of a slot 865 in a lever 866 pivoted on the stud 860. Clockwise movement of the lever 859, as above described, through the stud 863 rocks the lever 866 clockwise about the stud 860, and through the connection of a pin 867 with a slot 868 in the link 361 rocks said link counter-clockwise about the stud 362 and withdraws said link from the stud 359 on the spider 349.

The lever 866 has a slot 869 cooperating with a pin 870 on a lever 871 pivoted on a stud 872 on the plate 331. The lever 871 carries a pin 873. The lever 866, through the cooperation of its slot 869 with the pin 870, rocks the lever 871 counter-clockwise, whereby the pin 873 enters a notch 874 in the spider 349 and positively locks said spider in this position until one of the pins 347 has been engaged with one of the hooks 348 on said spider. Downward movement of the total lever 172 also rocks the shaft 438 clockwise, as previously described, thereby lowering the link 862 so that the stud 863 is moved downwardly a short distance, but not far enough to engage the cam portion of the slot 865.

Movement of the total lever 172 downwardly also connects the disk 795 (Fig. 2) with the gear 58 and moves the link 147 to such a position that the gear 58 is permitted to make one complete rotation, thereby giving

ing two rotations to the gear 60 and shaft 61.

After the parts have been moved to the positions just described by the total lever 172 the motor is released to give the shaft 61 two complete rotations in a clockwise direction.

During the first rotation of the shaft 61 (Fig. 5) the lever 363 is rocked clockwise and moves the link 361 to the right and positions a notch 880 therein directly above a pin 881 on the spider 349. Immediately after this has taken place the cam race 800 (Fig. 2) moves the link 785 to the left and rocks the shaft 438 still farther in a clockwise direction thus moving the link 862 downwardly, whereby the stud 863, through its contact with the cam portion of the slot 865, rocks the lever 866 still farther clockwise and, through the connection of its pin 867 with a slot 868, rocks the link 361 still farther counter-clockwise about the stud 362 and moves the notch 880 over the pin 881 on the spider 349. The lever 866 also, through the cooperation of its slot 869 with the pin 870, rocks the lever 871 clockwise and withdraws the pin 873 from the notch 874. After the notch 880 embraces the pin 881, and during the last part of the first rotation of the shaft 61, the lever 363 is rocked counter-clockwise and moves the link 361 to the left, thereby rotating the spider 349 clockwise. This movement of the spider, through the connection of one of its hooks with one of the pins 347, rocks the selected totalizer shaft, as determined by the position of the total lever 172, into engagement with the totalizer actuators previously described. The totalizer is held in engagement with the actuators by the cams 367 and 368 until the actuators have been differentially positioned under the control of the long tooth 836 on the totalizer pinions 214 in the manner previously described, after which the lever 363 is rocked clockwise and moves the link 361 to the right, which rocks the spider 349 counter-clockwise, thereby disengaging the selected totalizer from the actuators. Immediately after the link 361 has been moved to the right the cam race 800 (Fig. 2) rocks the shaft 438 and arm 488 counter-clockwise and raises the link 862, which rocks the lever 866 counter-clockwise, thereby rocking the link 361 clockwise about the stud 362 and withdrawing its notch 880 from the pin 881. After said withdrawal the lever 363 is rocked counter-clockwise and moves the link 361 to the left to the position in which it was placed by the total lever 172.

After the link 361 is moved to the left, as last described, the total lever 172 is moved clockwise to its adding position, which rocks the lever 859 counter-clockwise and raises the link 862 and rocks the arm 488 and shaft 438 counter-clockwise to normal positions.

The link 862 rocks the lever 866 counter-clockwise to normal position and rocks the link 361 clockwise about the stud 362 so that the notch 360 again contacts the pin 359 on the spider 349.

From the above described operation it can be clearly seen that the totalizer selected by the total lever is rocked into engagement with the totalizer actuators before said actuators are moved differentially, and held in engagement therewith until the differential movement of the actuators under the control of the long tooth 836 on the pinion 214, is completed, after which said totalizer is rocked out of engagement with the differential actuators, thereby leaving the totalizer at zero.

The control of the engaging and disengaging of the totalizers with the actuators during sub-totalizing operations will now be described. For a sub-total operation the total lever 172 is moved in a clockwise direction (Fig. 5). This movement of said lever does not rock the lever 859 or the lever 866, as is the case in totalizing operations, because the slot 857 is concentric with the center of the stud 856 (Fig. 6) for all positions of the total lever 172 above its adding position. However, the total lever 172, through the connection of the slot 481 and pin 482, rocks the lever 483 counter-clockwise in identically the same manner as said lever is rocked during the totalizing operation above described to rock the shaft 438 clockwise, as above described, to connect the disk 795 (Fig. 2) with the gear 58.

In sub-totalizing operations the gear 58 receives one complete rotation and the gear 60 and shaft 61 receive two complete clockwise rotations, in identically the same manner as described in connection with the totalizing operations. As the lever 866 is not moved by the total lever 172 the link 361 remains in engagement with the pin 359 on the spider 349.

During the first clockwise movement of the lever 363 the link 361 is moved to the right and rocks the spider 349 clockwise and engages the selected totalizer with the differential actuator. After the totalizer has been engaged the cam race 800 (Fig. 2) moves the link 785 still farther to the left, thereby rocking the shaft 438 and arm 488 (Fig. 5) clockwise, which lowers the link 862, whereupon the stud 863 contacts the cam portion of the slot 865 and rocks the lever 866 clockwise about the stud 860. Clockwise movement of the lever 866 rocks the link 361 counter-clockwise about the stud 362 and withdraws the notch 360 from the pin 359 of the spider 349. The lever 866 also rocks the lever 871 counter-clockwise and its pin 873 engages a notch 882 in the spider 349 and positively locks said spider in this position, thereby holding the

totalizer in engagement with the actuators. Immediately after the withdrawal of the link 361 from the pin 359 the lever 363 is rocked counter-clockwise and moves the link 361 to the left. This movement of said link is idle because the link is not engaged with either the pin 359 or the pin 881. The selected totalizer is now engaged with the differential actuator and said actuator is moved differentially under the control of the long tooth on the totalizer pinions 214, thereby resetting said totalizer to zero. As previously described, the amount on the totalizer is now printed from the type wheels.

During the first part of the second rotation of the shaft 61 the differential actuators are again moved, and due to the fact that the totalizer pinions are engaged therewith the amount that was taken from said pinions is again accumulated thereon. The lever 363 is again rocked clockwise and moves the link 361 to the right and positions the notch 360 therein directly beneath the pin 359 on the spider 349. The cam race 800 (Fig. 2), at this time, moves the link 785 to the right and rocks the shaft 438 counter-clockwise and raises the link 862 (Fig. 5), which rocks the lever 866 counter-clockwise, and thereby rocks the link 361 clockwise about the stud 362 so that it again contacts the pin 359. This counter-clockwise movement of the lever 866 rocks the lever 871 clockwise and withdraws its pin 873 from the notch 882 to allow the spider 349 to be rocked. The lever 363 is then rocked counter-clockwise to normal position and moves the link 361 to the left, thereby rocking the spider 349 counter-clockwise, which disengages the totalizer from the actuators.

Total lever 172 is then moved counter-clockwise to its normal adding position, and, through the slot 481 and pin 482, rocks the lever 483 to normal position and raises the link 862 to the position shown in Fig. 5. The total lever, during the latter movement, also disconnects the disk 795 (Fig. 2) from the gear 58 so that said disk is not rotated while the total lever 172 is in the adding position.

From the above description it can be clearly seen that during a sub-totalizing operation the totalizer is engaged with the actuators and reset to zero by the movement of the actuator, but said totalizer is maintained in engagement until the actuators are again moved, which operation puts back on the totalizer the amount taken therefrom, so that at the end of a sub-totalizing operation the amount on the totalizer is the same as it was before the sub-totalizing operation was made.

The totalizing lever 172 is locked against manipulation, during the time the totalizers are being rocked into and out of engagement with their actuating mechanism, by a curved portion 887 (Fig. 5) of the spider 349 engaging a roller 888 carried on the yoke 177. As the spider moves clockwise the ear 178 on the yoke will be held in locked position with the notch 179 after the release shaft has carried the pin 175 away from the yoke 177.

Operation

A very brief description will now be given of an operation wherein an itemized receipt is issued, as illustrated in Fig. 29. Let it be assumed that a "cash" transaction including four separate items is made. The operator positions the totalizing lever 172 in the adding position, as shown in Fig. 1, depresses amount keys 110 representing the value of the first item, which is six dollars eighty-eight cents, the "Cash" key 152 and then the starting key 116, which releases the mechanism, allowing the machine to be operated either by the crank 55 or the electric motor. This amount will be entered in the "Cash" totalizer (Fig. 20) and printed upon the receipt (Fig. 29). At the end of the operation the amount keys will have been returned to normal positions but the "Cash" key will remain depressed so that in recording the other three items of the transaction the amount keys and the starting key only need be depressed. After recording the last item, in this transaction, four dollars and seven cents, the totalizing lever 172 is moved downwardly to the first notch 889. The starting key 116 is depressed and the machine operated. During this totalizing operation the transaction totalizer cooperates with the actuators to position the type wheels corresponding to the amount accumulated upon this totalizer, which amount is the total of the four items entered. This total, twenty-five dollars and seventy-five cents, is printed upon the receipt, together with the cash character, the date, consecutive number and other desired data, as shown in Fig. 29. At the same time this total amount is printed upon the total strip 551 (Fig. 28). Also, "one" will be added in the "Customer" counter 415 and on the "Cash" counter 890 (Fig. 10).

Transactions of different classifications, as represented by the keys 152 (Fig. 1), are recorded in a similar manner to the "Cash" transaction, the only difference being the depressing of the key 152 representing the transaction.

When it is desired to take a sub-total or reading from the classification totalizers, the lever 172 is moved upwardly to the notch 891, the classification key 152 depressed to select the totalizer, and the machine operated as before. The amount accumulated on this totalizer will be printed upon the total record strip 551 and the totalizer will still retain this amount at the

end of the operation. But, should the operator desire to print the total from a classification totalizer and reset the same to zero he will move the totalizer lever to the lower 5 notch 892, select the classification totalizer by depressing the key 152 and operate the machine as before.

While the form of mechanism herein shown and described is admirably adapted 10 to fulfill the objects primarily stated, it is to be understood that it is not intended to confine the invention to the one form or embodiment herein disclosed, for it is susceptible of embodiment in various forms all 15 coming within the scope of the claims which follow.

What is claimed is:

1. In a machine of the class described, capable of entering items and taking totals 20 thereof, a single set of printing wheels for printing both the items and the totals, a plurality of impression hammers for making an impression on record material from said printing wheels, means for disabling certain hammers when taking item impressions, and means to actuate the disabling means to release the disabled hammers when taking total impressions.

2. In a machine of the class described, a 30 rotating means for feeding record material, an oscillating means operating said rotating means, a movable member limiting the movement of said oscillating means, and automatic means for moving said movable 35 member so as not to limit the movement of said oscillating means.

3. In a machine of the class described, cylindrical feeding means for record material, an oscillating means operating said 40 cylindrical feeding means, a lateral projection on said oscillating means, a movable member normally in the path of movement of said projection to control the movement of said oscillating means, and automatic 45 means to change the location of the movable member relative to the lateral projection, thus rendering the movable member ineffective as a controller of said oscillating means.

4. In a machine of the class described, a 50 rotating means always movable in the same direction for feeding record material, an oscillating means having, first a spring actuated movement, and then a positively actuated return movement to operate said rotating means, a movable member normally 55 in the path of said oscillating means to normally limit the spring actuated movement of said oscillating means, and automatic means for shifting said movable member out of the path of said oscillating means, whereby the oscillating means is given its full spring actuated movement.

5. In a variable feeding mechanism for 60 feeding record material, the combination of a feeding roller, a segment gear actuator, a

spring for driving the segment gear to variable extents, an obstruction adapted to normally limit the extent of movement of said segment gear, and automatic means for removing said obstruction to permit said segment gear to move its full extent of movement. 70

6. In a variable feeding mechanism for feeding record material, the combination of a feeding roller having a pawl and ratchet to feed in a single direction, a segment gear to drive the pawl, a spring for driving the segment gear to variable extents in one direction, positive means, including an extension of the segment gear and a cam actuated device cooperating with the extension to return said segment gear to its normal position, an obstruction adapted to normally limit the extent of movement of said segment gear when driven by said spring, and automatic means for removing said obstruction whereby the spring moves said segment gear its full extent. 80

7. In a machine of the class described, adapted to make single and double cycles, 90 the combination of a variable feeding mechanism for feeding record material, a segment gear actuator, a spring for driving the segment gear to variable extents, a projection carried by said segment gear, a movable 95 member engaging said projection to normally limit the extent of movement of said segment gear, a projection on said movable member engaging the projection on said segment gear during the two cycle operation to prevent the movable member from being moved out of engagement with said segment gear projection during the first cycle of operation.

8. In a machine of the class described operable in one and two cycle operations, mechanism to control the machine for a two-cycle operation, means for feeding record material during a one cycle operation and during the first cycle of a two cycle operation, and means actuated by the two-cycle control mechanism for controlling said feeding means to feed a greater distance during the second cycle of operation. 100

9. In a machine of the class described, the combination of an operating means, a plurality of impression hammers, a record material feeding device, a pivoted member having a projection, means on each impression hammer adapted to be engaged by said projection, and a manually operable lever for moving said pivoted member to engage the projection thereon with the means on both hammers to disable said impression hammers, said manually operable lever adapted to simultaneously disable said record material feeding device at will. 110

10. In a machine of the class described, the combination of a control lever having an adding position and a total position, a 120

- counting device, an oscillating member, a reciprocating member attached to said oscillating member to operate said counting device, a movable member supporting said reciprocating member in position to operate said counting device, a second oscillating member adapted to operate said movable member, and means operated by said control lever, when moved into said total position, to operate said second oscillating member and disengage said reciprocating member from said counting device.
11. In a machine of the class described, means for controlling the machine to perform operations of one or two cycles, an operating means, a counting device inoperable during a one-cycle operation, means operated by said controlling means to make said counting device operable during a two-cycle operation, and means operated by said operating means to operate said counting device during the first cycle of a two-cycle operation.
12. In a machine of the class described, a counting device, a manipulative device, a rocking member adapted to be operated upon operation of said manipulative device, means intermediate said rocking member and said counting device for operating said counting device, a second manipulative device, a second rocking member operated by said second manipulative device, and means intermediate said second rocking member and said first intermediate means for rendering said counting device operating means ineffective.
13. In a machine of the class described, a counter, means for releasing the machine, means operated by the releasing means for operating the counter, and total control means for rendering said operated means ineffective.
14. In a machine of the class described adapted to perform operations of one and two cycles, means for releasing the machine to perform said operations, a counter, means operated by the releasing means in a one-cycle operation to operate said counter, and means, operable preliminarily to a two-cycle operation, to render said counter operating means ineffective upon operation of the releasing means.
15. In a machine adapted to perform operations of one and two cycles, a releasing means, a counter, means operated by the releasing means during one-cycle operations for operating said counter, and means for controlling the machine to perform a two-cycle operation and for rendering said counter operating means ineffective.
16. In a machine of the class described, a counter, means for controlling the machine to make two cycles of operation, a counter actuating mechanism set to effective position by the control means and means operated in a two cycle operation for operating said actuating mechanism to actuate said counter.
17. In a machine of the class described, adapted to make single and double cycles; type carriers settable during each single cycle and double cycle operation; impression hammers to coact with the type carriers one of said hammers adapted to act alone, or in combination with another to produce records of different characters; means to disable one of the impression hammers during each single cycle operation, whereby the other hammer operates alone to produce one character of record; means effective to disable all of the impression hammers during the first cycle only of each double cycle operation; and means to render the effective means ineffective during the second cycle of the double-cycle operation, to enable all of the hammers to operate to produce a record of a different character from that produced by the sole operation of one of the hammers.
18. In a machine of the class described, adapted to make single or double cycles; type carriers settable during each single or double cycle operation; impression hammers to coact with the type carriers; operating means for the impression hammers operable during every cycle of operation; and means effective to disable all the hammers during the first cycle of each double cycle operation, said means being ineffective during the second cycle of a double cycle operation.
19. In a machine of the class described, the combination with a series of type carriers arranged in axial alignment; of an impression hammer to coact with the type carriers located intermediate the end of the series; and an impression hammer recessed to clear the first mentioned impression hammer and cooperating with the first mentioned hammer to print from all the type carriers.
20. In a machine of the class described, adapted to receive item entries and to print totals of the items entered, in combination with a series of type carriers arranged in axial alignment; of an impression hammer to coact with certain type carriers of the series for printing items; and an impression hammer recessed to clear the first-mentioned hammer to coact with other type carriers of a series; and operating means to cause both hammers to coact with the entire series of type wheels for printing totals.
21. In a machine of the class described, capable of making double cycle operations; a normally active impression hammer; a normally inactive impression hammer; means for setting the machine for a double cycle operation; means operated by the setting means to render the normally active hammer inactive during the first cycle of a double cycle operation; and means operated

by the machine to render both hammers active during the second cycle of a double cycle operation.

22. In a machine of the class described, capable of making double cycle operations; a normally operable impression hammer; means for setting the machine for a double cycle operation; a device positioned by the setting means to coact with the impression hammer to render the impression hammer inactive during the first cycle of a double cycle operation; and means operable during the first cycle of a double cycle operation to render the device ineffective during the second cycle of a double cycle operation.

23. In a machine of the class described, the combination of means to control a machine to perform one-cycle operations to accumulate items of a multiple-item transaction, and two-cycle operations to print a total of each multiple-item transaction; means, operated upon release of the machine for one-cycle operations, to count "one" to determine the number of items accumulated; means, operated during a two-cycle operation, to count "one" to determine the number of transactions entered; and means operated during the latter operation to prevent operation of the means for counting one-cycle operations.

24. In a machine of the class described, the combination of item type elements; total type elements employed in conjunction with the item type elements to print totals; impression means adapted to print from the item type elements; and a total control lever adjustable to prepare the machine for total-taking operations and to control the impression means to print from the item and total type elements during total-taking operations.

25. In a machine of the class described, the combination of a plurality of printing hammers; a common actuator therefor; an arm secured to each hammer, said arms being located side by side; lateral projections on said arms; and means interposed between the arms and adapted to cooperate with the lateral projections to select a hammer for actuation.

26. In a machine of the class described, the combination of a plurality of printing hammers; a common actuator therefor; an arm secured to each hammer, the arms being located side by side; lateral projections on said arms; means interposed between the arms and adapted to cooperate with the lateral projections to select a hammer for actuation; and a manipulative device for positioning said means.

In testimony whereof I affix my signature.
BERNIS M. SHIPLEY.

CERTIFICATE OF CORRECTION.

Patent No. 1,817,883.

Granted August 4, 1931, to

BERNIS M. SHIPLEY.

It is hereby certified that error appears in the printed specification of the above numbered patent requiring correction as follows: Page 4, line 14, strike out the word "normally"; page 8, line 58, for "levers" read bell cranks; page 23, line 72, claim 17, after the word "carriers" insert a comma; and that the said Letters Patent should be read with these corrections therein that the same may conform to the record of the case in the Patent Office.

Signed and sealed this 22nd day of September, A. D. 1931.

(Seal)

M. J. Moore,
Acting Commissioner of Patents.
